HEEL AND SHANK LASTING MACHINES

Sidney J. Finn, Beverly, Mass., assignor to United Shoe Machinery Corporation, Boston, Mass., a corporation of New Jersey

Application May 5, 1955, Serial No. 506,133

87 Claims. (Cl. 12—8.5)

This invention relates to lasting machines and is herein illustrated as embodied in a machine for lasting the heel ends and adjacent shank portions of shoes which in some respects represents an improvement of the lasting machine disclosed and claimed in United States Letters Patent No. 2,748,403, granted June 5, 1956, on an application filed in my name. It will be understood, however, that in certain aspects the present invention is of broader utility and hence not limited to use in a machine for lasting both the heel end and the shank portions of a shoe at the same time or to embodiment in the exact mechanical construction herein disclosed.

An object of the invention is to provide a novel and improved machine for lasting the heel ends and shank portions of shoes which is very dependable and efficient in operation and, at the same time, is capable of handling a wide range of different sizes and styles of shoes with a minimum amount of operator skill and labor. With that purpose in view, the herein illustrated machine, which like the prior machine of the above-mentioned patent is intended primarily for, but by no means limited to, use in the lasting with adhesive of the heel ends and adjacent shank portions of shoes, the toes and foreparts of which have previously been lasted, for example, in a machine of the type illustrated in United States Letters Patent No. 2,703,420, granted March 8, 1955, on an application filed in my name, is provided with a pair of heel seat wipers for wiping the lasting margin of the upper materials around the heel end of a shoe inwardly over the bottom of the shoe and two groups of shank wiping elements each including a number of shank wipers for wiping the lasting margin of the upper materials along the shank portions at the opposite sides of the shoe inwardly over the bottom of the shoe. These heel seat wipers are mounted for rectilinear advancing movements toward the shank wiping elements and for arcuate swinging closing movements and initially are separated from the shank wiping elements, while the shank wiping elements are mounted for advancing movements in directions extending toward the opposite sides of the shoe.

In accordance with a feature of the invention, the herein illustrated machine is provided with a pair of intermediate wipers each of which is operatively associated with a heel seat wiper and a shank wiper in such a manner that the wipers present a substantially continuous and uninterrupted wiping surface to the upper materials as the heel seat wipers are advanced and closed and the shank wipers advanced. More particularly, each of these intermediate wipers is pivotally connected to a shank wiping element and is slidably received in one of the heel seat wipers so that the intermediate wipers are free to move inwardly with the shank wiping elements and to telescope within the advancing heel seat wipers as the heel seat wipers are advanced and closed and the shank wiping elements advanced. With this novel and improved arrangement, the upper materials are wiped smoothly in over the bottom of the shoe at the heel end

2

thereof and in the shank portions at the opposite sides of the shoe without any line of demarcation between the zone of action of the heel seat wipers and that of the shank wiping elements. Preferably, the heel seat wipers are adapted to be advanced by fluid pressure operated means and during such advancing movement are closed by additional fluid pressure operated means, the latter being under the control of cams which control the swinging movements of these wipers in accordance with the advancing movements thereof. Thus very powerful yet accurately controlled advancing and closing movements are imparted to these wipers without, however, subjecting the aforementioned cams to undue stress and wear.

The two groups of shank wiping elements of the herein illustrated machine each comprise a plurality of articulated shank wipers or wiping elements which are contiguously arranged so as to provide a substantially continuous and uninterrupted wiping surface and these two groups of elements are each supported on a carrier which is mounted for advancing movement toward the shank portion of a shoe being lasted. Moreover, the shank wiping elements of each group are so arranged that the wiping surface thereof has a flat portion and a curved portion for operating, respectively, on the flat and curved portions of the shank of the shoe. In order to accommodate shoes of different sizes and/or styles, there is, in accordance with a further feature of the invention, associated with each carrier a control member which is movable relatively to the carrier for varying the positions of the shank wiping elements to vary the contour of the wiping surface provided by these elements. More particularly, each of these control members is movable, relatively to its associated carrier, in a direction extending lengthwise of the shoe being lasted to change the positions of the flat and curved portions of the wiping surface in directions extending lengthwise of the shoe thereby to vary the contour of the wiping surface to accommodate shoes of different sizes and is movable angularly, relatively to the carrier, for varying the positions of the wiping elements to change the angular relationship between the flat portion and the curved portion of the wiping surface to vary the contour of the wiping surface to accommodate shoes of different styles. In the herein illustrated machine, the angular movements of the two control members are effected manually by the operator while the movements of the control members in directions extending lengthwise of the shoe are effected automatically by power operated means, prior to movements of the carriers to advance the shank wiping elements toward the shoe, and the extent of movement of each of the control members in a direction extending lengthwise of the shoe is limited by a member which is movable with each control member and engageable with the curved part of the shank portion on that side of the shoe so that the contour of the wiping surface is automatically determined in accordance with the size of the particular shoe then being lasted.

For augmenting the action of the heel seat wipers and of the shank wipers to draw the lasting margin of the upper materials inwardly over the bottom of the shoe and to cause these wipers to exert a substantial pull for tensioning the upper materials about the last, the herein illustrated machine is provided with a plurality of retarder fingers, certain of which are adapted to cooperate with the heel seat wipers while others are arranged to cooperate with the shank wipers. Preferably, and as herein illustrated, the retarder fingers which cooperate with the heel seat wipers are associated with a fluid pressure operated abutment member arranged to be moved into a position for engaging the heel seat portion of the insole of the shoe being lasted to determine the heightwise position

of the shoe relatively to the wipers during the operation of the machine. Initially, this abutment member is positioned remote from the bottom of the shoe and during its movement, by the mentioned fluid pressure operated means, to an operative position for engagement with the insole of the shoe, the retarder fingers associated therewith are moved to their operative positions by means which are arranged to yield and thereby permit movement of the fingers inwardly in response to pressure of the upper materials thereagainst by the inwardly moving heel seat wipers. When in their operative positions, these heel seat retarder fingers are arranged to project somewhat beyond the aforementioned abutment member and are moved, relatively to the abutment member, against the resistance of spring means, so that they serve as insole holdowns for pressing the marginal edges of the heel seat portion of the insole yieldingly against the bottom of the last, during a continued movement of the abutment member prior to its engagement with the insole. More particularly, a pair of plungers are mounted adjacent to the abutment member for sliding movements relatively thereto of extents which are limited by cooperating stop means on the plungers and the abutment member and which are resisted in one direction by springs. The retarder fingers are pivotally mounted on these plungers, and connected to these fingers are yieldable means which are arranged to swing the retarder fingers to their operative positions in response to movement of the abutment member toward the shoe. When in their operative positions, these retarder fingers project somewhat beyond the abutment member so that they first engage the marginal edge of the heel seat of the insole and are then moved yieldingly heightwise of the shoe against the resistance of the mentioned springs during the continued movement of the abutment member prior to its engagement with the insole. When the heel seat wipers are operated to wipe the lasting margin of the upper materials inwardly over the bottom of the insole, these fingers are swung inwardly against the resistance of the aforementioned yieldable means and thus cause the heel seat wipers to exert a tensioning pull on the upper materials.

The other retarder fingers which are arranged to cooperate with the shank wipers are also pivotally mounted for inward swinging movements against the resistance of spring means to which they are releasably connected by means of toggle links. Initially, these shank retarder fingers are positioned in locations remote from their points of engagement with the insole of the shoe in directions extending both heightwise and lengthwise of the shoe and the toggles formed by the mentioned links are broken. During an early stage in the automatic operating cycle of the machine, the toggles formed by these links are first straightened to move the associated retarder fingers in a heightwise direction toward the insole and thereafter these fingers are moved bodily in a direction extending lengthwise of the shoe until the retarder fingers on the opposite sides of the shoe which are located closest to the toe end of the shoe are brought into engagement with the insole in the upwardly curving part of the shank portion of the shoe. Conveniently, and as herein illustrated, the means for thus moving the shank retarder fingers in directions extending lengthwise of the shoe is also arranged to effect movement of the aforementioned shank wiper control members relatively to the shank wiper carriers and the engagement of the shank retarder fingers with the insole in the upwardly curved shank portion of the shoe thus serves to limit the movement of the control member for the purpose set forth above. During the advancing movements of the shank wipers, these retarder fingers are swung inwardly against the resistance of the spring means to which they are connected by the toggle links, thus causing the shank wipers to exert a tensioning pull on the upper materials. Eventually, the toggles formed by these links are broken, by suitable cam means, thus releasing the retarder fingers for movement

to their inoperative positions and providing clearance space for the further advance of the shank wipers.

In order to facilitate the lasting operation, the herein illustrated machine, in accordance with a further feature of the invention, is provided with means for automatically presenting the shoe to be lasted to the machine in the correct operating position relatively to the wipers regardless of the size of the shoe. This means includes a movable support or carrier on which the shoe to be lasted is placed by the operator while the carrier is in a convenient loading position. Thereafter, upon the initiation of an automatic operating cycle of the machine in response to the depression of a foot treadle, the carrier is moved, preferably by fluid pressure operated means, from its inoperative or loading position to an operative position and means controlled in accordance with the size of the shoe on the carrier are provided for limiting the extent of such movement of the carrier to cause the carrier when in said operative position to locate the shoe in the same lengthwise position, relatively to the wipers, regardless of its size. More particularly, the carrier is first moved from its inoperative position inwardly of the machine somewhat beyond the operative position and thereafter is moved outwardly to the operative position, this outward movement being effected by means including a pair of shoe centering arms the movements of which are controlled in accordance with the size of the shoe on the carrier thereby to limit the extent of such outward movement in such a way that the carrier when in its operative position locates the shoe thereon in the same lengthwise position, relatively to the wipers, regardless of its size.

Associated with the carrier is a stop member for engaging a shoe placed on the carrier to determine the heightwise position of the carrier and also of the shoe thereon prior to the movement of the carrier from its loading position to its operative position and means are provided for automatically withdrawing this stop member during the movement of the carrier to its operative position thereby removing the stop member from the path of the heel seat wipers when they are subsequently advanced and closed. Immediately after the carrier has thus moved to locate the shoe thereon in a proper lengthwise position relatively to the wipers, the fluid pressure operated abutment member, which has been mentioned above, is moved downwardly and into engagement with the insole at the heel end of the shoe thereby slightly depressing the carrier to position the shoe in the proper heightwise location relatively to the wipers. Now the carrier is forced upwardly by power operated means, herein illustrated as fluid pressure actuated, to clamp the shoe firmly against the abutment member during the operation of the wipers. In order to prevent retrograde movement of the carrier during the operation of the wipers, there is associated with the fluid pressure operated means, utilized to move the carrier inwardly of the machine to its operative position, a valve which is normally open to admit fluid under pressure to the carrier moving means and which is arranged to be closed in response to the actuation of the wipers thereby trapping operating fluid and locking the carrier against retrograde movement.

As indicated above, the abutment member which is moved into engagement with the insole to determine the heightwise position of the shoe on the carrier relatively to the wipers is actuated by fluid under pressure. For the purpose of augmenting the action of the wipers to press the lasting margin of the upper materials firmly against the bottom of the shoe and thus to facilitate the adherence of the upper to the insole, the herein illustrated machine is provided with a valve which is normally adapted to admit fluid under pressure to the fluid pressure operated means for moving this abutment member and with means operable during the inward movement of the wipers for shifting this valve to a position for con-

necting the mentioned fluid pressure operated means to exhaust, thereby causing the carrier to be elevated by its operating means to press the shoe against the wipers with increased force.

Because of the above referred to action of the wipers to exert substantial tensioning pulls on the upper materials, the herein illustrated machine, in accordance with a further feature of the invention, is provided with a flexible U-shaped band for embracing the heel end and adjacent shank portions of the shoe being lasted to press the upper materials firmly against the last and thereby to prevent distortion or displacement of these materials relatively to the last during the operation of the machine. As herein illustrated, this band is located initially in a position to engage the heel end of a shoe on the carrier when the carrier is in its loading position and is mounted for movement with the carrier in response to pressure of the shoe thereon as the carrier is moved to its operative position. Associated with the outer ends of this U-shaped band are springs which yieldably resist such movement of the band by the shoe as the carrier is moved to its operative position and, in thus resisting the movement of the band, cause it to be wrapped snugly around the heel end and adjacent shank portions of the shoe on the carrier. Further to augment the action of the band, the herein illustrated machine is also provided with fluid pressure operated means for pressing the band against the opposite sides of the shoe in the vicinity of the shank portion thereof.

The above and other objects and features of the invention will appear in the following detailed description of the embodiment thereof which is illustrated in the accompanying drawings, and will be pointed out in the claims.

In the drawings:

Fig. 1 is a view in side elevation of a lasting machine embodying the features of the invention;

Fig. 33 is a diagrammatic view of the fluid pressure operated mechanisms of the machine; and

Figs. 34 and 35 are diagrammatic views illustrating certain aspects of the operation of the machine.

Referring to the drawings, the machine which is illustrated therein is adapted to last the heel seat and adjacent shank portions of a shoe by means of a pair of heel wipers 50, 50 and a plurality of shank wipers 60, 60, see Fig. 28. Cooperating with these wipers to facilitate their lasting actions are a plurality of retarder fingers, there being two of these fingers 70, 72 on each side of the shoe for cooperating with the heel seat wipers, see Figs. 11, 12 and 15, and two fingers 74, 76 on each side of the shoe for cooperating with certain of the shank wipers, see Fig. 16. In order to accommodate right or left shoes of different sizes and of varying heel heights, the shank wipers are of a novel construction to be described below and are automatically set for the size of the particular shoe being lasted by mechanism which will also be described below. During the operation of the machine, the shoe S being lasted, herein illustrated as comprising an upper u and insole i assembled on a last l, is supported on a carrier, indicated generally by the reference character 30, see Figs. 3 and 5, and is positioned in a heightwise direction relative to the wipers by engagement of its heel seat with a heel abutment, or height gage 82, see Figs. 11 and 12. Arranged to embrace the heel end of the shoe is a flexible heel band 84, Fig. 3, this heel band being also adapted to extend forwardly of the shoe beyond its shank portion. For pressing the heel band firmly against the opposite sides of the shank portion of the shoe a plurality of side clamps 86, 86 are provided, see Figs. 8 and 18, while a pair of centralizing members 88, 88, see Fig. 8, are arranged to press the heel band against the opposite sides of the heel end of the shoe.

The several operating elements of the machine are operated in predetermined time relation by means of fluid pressure actuated pistons under the control of a plurality of sequence valves, fluid under pressure being supplied by means of a pump Y, driven by an electric motor Z which takes operating fluid, such as oil, from a sump 100 and delivers it to a main control valve A through a main pressure regulator valve X, see Fig. 33. For supporting the various operating elements the machine has a fabricated frame, indicated generally by the reference character 102, on which there is mounted a head casting having upper and lower portions 104 and 106, respectively, see Figs. 1, 2, 3, 11 and 12.

The shoe carrier 30 comprises a carriage 120 which is

slidably supported on a horizontally disposed cylinder 122, Fig. 5, and this cylinder in turn is secured to the upper end of a hollow plunger 124. The plunger 124 is fitted within a cylinder 125 having at its upper end a bracket 128 which is secured to a portion of the frame 102. At its lower end the cylinder 125 is embraced by a clamping ring 130 which is fastened to an upstanding portion of the frame 102. Contained within the hollow plunger 124 is a coil spring 132 which constantly urges the cylinder 122 and the carriage 120 upwardly to the extent permitted by the engagement of a step washer 134, carried by a stud 136 which is threaded into the lower side of the cylinder 122, with the lower side of the bracket 128. An adjusting screw 138 is provided for varying the compression of the spring 132. Also secured to the lower side of the cylinder 122 is a plunger 140 which projects downwardly into a hollow piston rod 142, secured to a piston 144. This piston is slidable within a cylinder 146 which is secured at its upper end to the frame 102 and the piston rod 142 has an extension 148 which engages an end wall 150 of the cylinder 146 to limit the movement of the piston in one direction. Conduits 152, 154 are connected to the interior of the cylinder 146 at spaced points located, respectively, above and below the piston 144.

As will be apparent, when fluid under pressure is admitted to the cylinder 146 through the conduit 154 and at the same time exhausted from the cylinder through the conduit 152, the piston 144 will be elevated until the upper end of the hollow piston rod 142 engages a shouldered portion 156 on the plunger 140 whereupon the cylinder 122, together with the carriage 120, will be moved upwardly, a portion of the weight of these parts being counterbalanced by the spring 132. Slidable within the cylinder 122 is a piston 160 which is connected to the carriage 120 by means of a piston rod 162 and a yoke member 164. Connected to the interior of the cylinder 122 on the opposite sides of the piston 160 are two conduits 166, 168. By admitting fluid under pressure through one of these conduits while at the same time exhausting fluid through the other, the piston 162 may be actuated to move the carriage 120 in one direction or the other relatively to the cylinder 122. The outer end of the piston rod 162 slides freely through a hole in the yoke member 164 so that a certain amount of movement of the carriage 120 relatively to the piston 160 is permitted as determined by a stop nut 170 and a shoulder 172 on the piston rod 162.

Slidably mounted in a direction extending lengthwise of the carriage within a guideway 174 is a block 176 having a vertically extending bore 178 in which there is received a hollow sleeve 180 adapted to be held in different positions of vertical adjustment by means of a finger pawl 182, Fig. 5. Slidable within the hollow sleeve is a plunger 184 which is yieldably supported by means of a compression spring 186 and held against rotation by means of a guide rod 188 fitted in a hole formed in the block 176 and projecting downwardly from a toe supporting member 190. For supporting the heel end of the shoe on the carriage 120 there is provided a block 192 which is mounted for movement in directions extending widthwise of the carriage by means of guideways 194, 194 and anti-friction rollers 196, 198 between limits determined by a stop abutment 200, see Fig. 7. Extending upwardly from this block is a last pin 202 which projects through clearance holes 204, 206 formed, respectively, in rocker blocks 208, 210. The lowermost block 208 is shaped to fit in a semi-cylindrical recess 212, formed in the block 192, while the uppermost rocker block 210 has an arcuate projection 214 adapted to rest in a similarly shaped recess 216 formed in the lower block 208. Thus the uppermost block 210 is free to rock in directions extending at right angles to each other when engaged by the heel cone surface of the last of a shoe placed on the carriage. This rocking action is facilitated

by the insertion of light coil springs 218, 218 between the block 192 and the lower rocker block 208.

The heel band 84 comprises a U-shaped strip of leather 230, Fig. 3, which is reinforced on its outer side by means of a layer of rubber 232. Secured to the inner part of the heel band is a bracket member 234 from which there extends rearwardly a hollow guide rod 236, Fig. 6. This rod is slidably supported within a bore 238 formed in a hollow piston 240, to be referred to below, see Figs. 10 and 18. Pivotedly mounted on the bracket member 234 is a U-shaped member 242 having two rearwardly extending arms 244, 244 on which are mounted rollers 246, 246, Fig. 6. On an upwardly extending portion 248 of the member 242 there is pivotally mounted an abutment member 250 which is yieldingly urged in a counterclockwise direction by means of a coil spring 252. A coil spring 254, stretched between a pin 256 on the bracket 234 and a pin 258 on one of the arms 244 of the member 242 yieldingly urges the member 242 in a counterclockwise direction to cause the abutment member 250 to lay within a notch 260 formed in the upper portion of the heel band with a part of this abutment member projecting somewhat beyond the heel band, see Fig. 5, to serve as a stop for limiting heightwise movement of a shoe S placed on the carriage. The bracket member 234 is provided with a downwardly projecting lug 262, Fig. 6, which is adapted to be received between two guide plates 264, 266 secured to the rearward end of the carriage 120, see Fig. 7, thereby preventing angular swinging movement of the heel band 84 about the axis of rod 236.

At each of its forward ends the heel band is connected to a rod 270, Fig. 3. Each of these two rods is slidable in the outer end of an arm 272 which is pivotally mounted at its inner end on the lower head portion 106. Coil springs 274, stretched between extensions of the arm 272 and projections on the lower head portion 106 tend at all times to swing these two arms yieldingly in the direction indicated by the arrows in Fig. 3. Such outward swinging movements of these arms is, however, limited by means of a stop rod 276 which is associated with the hollow guide rod 236, Figs. 10 and 18. This stop rod is provided at one end with an enlarged head 278 which fits within the guide rod, Fig. 18, while the smaller body portion of this rod is slidable through a bushing 280 pressed into the inner end of the guide rod. At its other end, the rod 276 is threaded and extends outwardly through a hole in an abutment member 282 which is secured to the head portion 284 of a cylinder 286, Figs. 3 and 10, in which the piston 240 is received, Fig. 18. A stop nut 290 on the threaded end of the rod 276 may be adjusted to vary the position to which the heel band is moved outwardly by the arms 272, 272 and spring 274. As will presently appear, the heel band is moved inwardly by the shoe as the carriage 120 is actuated to carry the shoe into the machine. When the heel band is thus moved inwardly it is wrapped around the heel end and opposite shank portions of the shoe so that the outer ends of the heel band tend to approach each other. During such approaching movement of the outer end of the heel band, the rods 270 slide outwardly of the arms 272 against the resistance of coil springs 292, 292 which are interposed between shoulder portions 294 on these arms and collars 296, 296 carried by the rods 270.

Each of the centralizing members 83 is formed on one arm of a bell-crank lever 300, Figs. 8 and 10. These bell-crank levers are pivotally mounted on studs 302 which are secured to a portion 304 of the lower head casting 106. The other arms of the two bell-crank levers 300 are connected, by means of links 306, to a cross piece 308 which is fastened to a forwardly extending portion of the hollow piston 240 by means of screws 310, Fig. 10. This forwardly extending portion of the piston 240 is turned down at 312 to fit within a cylindrical guide bore 314 formed in a block 316 which is secured to the portion 304 of the head casting 106 by means of screws 318.

Coil springs 320, connected between the opposite ends of the cross piece 308 and pins 322 mounted in the portion 304 of the head casting tend to hold the piston 240 in the retracted position in which it is shown in Figs. 8 and 18. However, when fluid under pressure is admitted to the cylinder 286 behind the piston 240, through a conduit 324, Fig. 18, the piston 240 and cross piece 308 will be urged forwardly and the centralizing members 88 will be swung toward each other and into engagement with the opposite sides of the heel band 84 thereby to centralize the heel end of the shoe in the machine in a manner which will be apparent and as permitted by the widthwise movement of the block 192, Fig. 7. As the cross piece 308 and piston 240 are thus moved forwardly the heel band 84 will be moved in the same direction by virtue of the engagement of the end 312 of the piston 240 with a shoulder on the bracket 234. Thus, since the extent of such forward movement of these parts will be limited by the amount of swinging movement of the centralizing arms, each shoe will be located in the same lengthwise position, relatively to the heel and shank wipers, regardless of its size. A second conduit 326 connected to the cylinder 286, in front of the piston 240, drains pressure fluid which may leak past the piston back to the sump. Secured to the lower side of the cross piece 308 are two cam members 328, 328, Fig. 10, the purpose of which will presently appear.

Each of the side clamps 86 comprises an upstanding body portion 340 which is secured to the outer end of a piston rod 342 having formed integrally thereon a piston 344, Figs. 8 and 9. Each of the pistons is slidably mounted in a cylinder bore 346 formed in a cylinder block 348, there being two of these cylinder blocks, one on each side of the machine, and four side clamps associated with each block. Formed in each of the cylinder blocks are two passages 350, 352, Fig. 9, which are connected, respectively, to each cylinder bore 346 on the opposite sides of the piston 344 therein and associated with each cylinder block is a header 354 provided with two passages 356, 358, Fig. 8, which are connected, respectively, to conduits 360, 362, Figs. 1, 18 and 33. The arrangement is such that when fluid under pressure is admitted to the conduits 360 and exhausted through the conduits 362, the side clamps 84 will be forced inwardly into engagement with the heel band on the opposite sides of the shank portion of the shoe, while the admission of fluid under pressure to the conduits 362 and simultaneous exhaust of fluid from conduits 360 will cause the side clamps to be retracted to the positions shown in Fig. 8. In order to hold the side clamps against rotation, downwardly extending portions 364 thereof are bifurcated and fitted over pins 366, mounted in the cylinder blocks 348, Figs. 9 and 18.

The heel abutment or height gage 82 comprises a plunger 380, having an upper cylindrical portion 381 which is slidably mounted in a bore 382 formed in the upper head casting 104, Fig. 11. Threaded onto the upper end of this plunger is a head piece 384 having a flat upper surface 386 and a peripheral portion provided with gear teeth 388, Fig. 14. Secured to the upper part of the head casting 104, by means of screws 390, is a cylinder 392 in which there is slidably mounted a hollow piston 394. This piston fits over a cylindrical projection 396 formed integrally with a cylinder head 398 which is secured to the cylinder 392 by means of screws 400. A coil spring 402, stretched between a pin 404 in the lower part of the plunger 380 and a pin 406 in the head casting 104 tends to hold the plunger yieldingly in its upper position, see Fig. 11, with the surface 386 bearing against a boss 408 on the piston 394. When fluid under pressure is admitted through a conduit 410 and a passage 412 to a space 414 formed on the lower side of the projection 396, the plunger 380 will be forced downwardly to the extent permitted by the engagement of the lower side of the head piece 384 with an upper surface 416 formed on

the head casting. For rotating the head piece 384, to vary the extent of downward movement of the plunger 380, a rack bar 420 is slidably mounted in a groove 422 cut in the lower side of the cylinder 392, Fig. 13, the teeth 424 of this rack bar meshing with the teeth 388 of the head piece 384. A spring-pressed plunger 426 having an inner end adapted to fit between adjacent teeth on the rack bar is provided for holding this bar in different positions to which it may be moved when the pin is withdrawn. Operating fluid leaking past the piston 394 and the cylindrical projection 396 is collected in an annular groove 430 and is conducted downwardly through a bore 432 to a drain passage 434, Fig. 14, to which there is connected a return pipe 436, Fig. 12.

Secured to the lower end of the body portion of the plunger 380 is a button 440 for engaging the heel seat of a shoe and an abutment 442 for engaging the shoe bottom in a location somewhat forwardly of the heel seat, this abutment being supported on a bracket 444 which is fastened to the body portion of the plunger, Figs. 11 and 15. Slidably mounted in bores formed in the head casting 104, on the opposite sides of the plunger 380, are two similar plungers 450, 450, Figs. 11 and 12, which are connected together at their lower ends by means of a cross-piece 452. Associated with each of these plungers are two coil springs 454, 456 which urge these plungers downwardly, relatively to the plunger 380, to the extent permitted by stop screws 458 which extend into elongated slots 460 in the lower end of the plunger 380, Fig. 12. The springs 454, Fig. 11, bear at their upper ends on pins 462, 462 which are carried by the plunger 380 and which project through slots in the plungers 450, while the springs 456, Fig. 15, are interposed between shoulders on the plungers 450 and plates 464, 464 secured to the head casting 104.

The heel retarder fingers 70, 72 are pivotally mounted on pins 470 carried on the lower ends of the two plungers 450, Figs. 11, 12 and 15. Connected to each of these fingers is the lower end of a coil spring 472 the upper end of which is fastened to one of the plates 464. When the plunger 380 and the plungers 450 are in their uppermost positions, as shown in Figs. 11 and 12, these springs are fully relaxed and serve as push rods to swing the fingers 70, 72 to the retracted positions in which they are shown. However, upon the downward movement of the plunger 380 and the plungers 450, the retarder fingers are swung yieldingly outwardly toward operating positions adjacent to the marginal edges of the insole *i* of the shoe *S* in the machine see dotted line positions, Fig. 11. Stop abutments on these fingers engage the lower part of the plunger 380 to limit such outward swinging movements of the fingers. When the fingers 70, 72 are in these operating positions, they project a short distance below the button 440 and abutment 442. Thus, when the carriage 120 is elevated to move the heel seat of the shoe into engagement with the button 440 and abutment 442, after the plunger 380 has been moved downwardly, the fingers 70, 72 serve as insole hold-downs as they are elevated by the shoe against the resistance of springs 454, 456. As will presently appear, the fingers 70, 72 function as retarders during the operation of the heel seat wipers 50, 50 and before these wipers complete their inward wiping actions, the plunger 380 is elevated by the spring 402, as fluid under pressure is exhausted from the space 414 above the piston 394, thus returning the parts to the positions shown in Figs. 11 and 12.

The shank retarder fingers 74, 74 each comprise, in effect, the inner jaw of a shank gripper having an outer jaw 480, see Figs. 24, 25, 26 and 27, while the shank retarder fingers 76, 76 each comprise the inner jaw of a gripper having an outer jaw 482, Figs. 2, 17 and 18. These grippers are all of a similar construction which will be described by reference to the foremost gripper on the left-hand side of the machine which is shown in detail in Fig. 17 and the rearmost gripper on the same side of the

machine shown in Figs. 24 to 27. The finger 74 (76) is pivotally mounted on a pin 490 carried by an outwardly extending arm 492 formed on a block 494 (530) and also pivotally mounted on this pin is the outer jaw 480 (482). The blocks 494 are formed integrally on the forward ends of two slides 496, 496, Fig. 16, which are mounted for sliding movement in guideways formed by gibs 498, 500, Fig. 23, secured to the upper surface of a cover plate 502 associated with the lower head casting 106, Figs. 16, 18, 22 and 23, and these slides are provided with arms 534, one of which carries a roller 503 which fits loosely in a slot 503 formed in the other arm, Fig. 16. The finger 74 (76) has an upwardly extending arm 512 which is connected to a plunger 514 by means of a pair of toggle links 516, 518, Figs. 17 and 24. This plunger has a head portion 520 which is slidable within a sleeve 522 fitted in the block 494. A coil spring 524 interposed between this head portion and an abutment plug 526, threaded into the sleeve, tends to urge the plunger 514 to the right, Fig. 24, so that the head portion 520 bears against a stop washer 528, Fig. 17. A coil spring 530 is stretched between the arm 512 and the plunger 514 and a grasshopper spring 532 is interposed between the finger 74 and the outer jaw 480.

Initially, each of the shank grippers (i. e., 74, 480, 74, 483, and 76, 482, 76, 482) is in an open position similar to that illustrated in Figs. 17 and 24, with the toggle links 516, 518 broken, fingers 74 (or 76) held in the position shown by the coil spring 530 and the outer jaw 480 (or 482) held in the position shown by the spring 532. Each of the fingers 74, 74, 76, 76 is provided with a projection 540 which, as will presently appear, is engaged by a downwardly moving abutment member early in the cycle of operation of the machine. As a result of the action of these abutments, the fingers 74, 74, 76, 76 are each moved to the position shown in Fig. 25 in which the toggles 516, 518 are straightened. During the inward movement of the shank wipers 60, 60 the outer jaw 480 (or 482) is first urged inwardly toward the edge of the bottom of the shoe S until the margin of the upper u is gripped between the outer jaw and the finger 74 (76), Figs. 25, 26. Upon the continued movement of the shank wipers, the outer jaw 480 (482) and finger 74 (76) are swung inwardly to exert a tensioning action on the upper u, Fig. 26, and the plunger 514 is forced outwardly against the resistance of the spring 524. Eventually a screw 542 carried by the toggle link 518 rides up on a cam member 544, Fig. 24, thus breaking the toggle 516, 518 and causing the finger 74 (76) to be swung by the spring 530 to a position, determined by a stop abutment 534 on link 516, Fig. 17, thereby to release the upper. As the inward movement of the shank wipers is completed, the parts assume the positions shown in Fig. 27, with the shank wipers 60, 60 inserted beneath the grippers. The shank grippers 76, 482, 76, 482 are each associated with one of the two blocks 550, corresponding to the block 494, Figs. 16 and 18, and each of the blocks 550 is connected to its companion block 494 by means of an upper and lower set of parallel links 552, 554, Fig. 24. A spring 556, Fig. 16, is arranged to elevate the block 550 relatively to its companion block 494, for a purpose which will presently appear.

As explained above, the shank fingers 74, 76 on each side of the machine are moved to their operating positions early in the operating cycle of the machine by means of two abutment members. Referring to Fig. 15, these abutment members comprise a stud 560 threaded into a head member 562, formed on the lower end of a rod 564, and a plunger 566 which is slidably mounted in the head member and urged yieldingly downward by means of a coil spring 568 to the extent determined by stop nuts 570, see also Figs. 17 and 24. Each of the rods 564 is connected at its upper end to an arm 572 which is secured to one end of a shaft 574 and is guided for vertical movement by means of a guide hole formed in a bar 576

secured to the plunger 380, Fig. 11. These shafts are journaled on the upper head casting 104 and have secured to their other ends arms 578, Figs. 1 and 12. The arms 578, 578 are each connected by means of a link 580 to one end of arm 582 which is formed integrally with a hub member 584 on which there is rotatably mounted another arm 586. This hub member is journaled on a stud 583 carried by a part of a head casting 104 and the arm 586 is adapted to be rotated in one direction or the other by a piston 590 to which one end of the arm 586 is connected by a link 592. The other end of the arm 586 is connected by means of toggle links 594, 596 to the arm 582 and these links are yieldingly held in straightened relation by a spring 598. The piston 590 is fitted within a cylinder 600 and is normally held in the retracted position in which it is shown in Fig. 12 by means of a spring 602.

When fluid under pressure is admitted to this cylinder, through a conduit 604, the arm 586 will be rotated in a counterclockwise direction, Fig. 12, and through the action of the toggle links 594, 596, the arm 582 will be turned in the same direction. As a result of such turning movement of the arm 582, the rods 564, 564 will be moved downwardly. At this particular point in the operating cycle of the machine, the slides 496, 496 on which the shank retarder fingers are supported, will be in the retracted positions shown in Fig. 16, and the abutment members, i. e., studs 560, 560 and plungers 566, 566 located directly over the projections 540 (Figs. 17 and 24) on the fingers 74, 74, 76, 76. Therefore, these fingers will be moved to their operating positions, see finger 74 in Fig. 25, by these abutment members. Just as these fingers reach their operating positions, in which the toggle links 516, 518 are straightened, an arm 610 formed on the toggle link 594 strikes an abutment 612, mounted on the head casting, thereby causing the toggle formed by the links 594, 596 to be broken to permit a coil spring 614, stretched between the arms 578, 578, Fig. 12, to return the rods 564, 564 and the abutment members carried thereby to their elevated positions as determined by stop blocks 616, 616 which are engaged by the arms 578, 578. At the conclusion of the operating cycle of the machine, the conduit 604 is connected to exhaust and the piston 590 is returned to its retracted position by the spring 602. During this movement of the piston, the toggle formed by the links 594, 596 will be restored to its straightened condition by the spring 598. Operating fluid which may leak past the piston 590 is returned to the sump through a drain conduit 618.

Each of the heel seat wipers 50 comprises a segmentally shaped plate which is provided on its lower face with an arcuate rib 620, adapted to fit in an arcuate groove 622 formed in a wiper carrier 624, Fig. 29. Fastened to the upper side of this carrier by screws 625 is a plate 626 provided with an arcuate surface 628 which is complementary to the outer arcuate edges of the two heel seat wipers 50, 50, see also Fig. 28. Each wiper carries an anti-friction roller 630 which bears against the surface 628 on the plate 626. Secured to the lower side of each wiper 50, by means of screws 632, are two guide blocks 634, 636, Fig. 29, between which there is loosely mounted a telescoping intermediate wiper 638, this wiper being adapted at certain times during the operating cycle of the machine to project beyond the wiper 50 and into a clearance space 640 formed in the plate 626, see also Fig. 4. The carriage 624 is slidably mounted in guideways 642 formed in a portion of the lower head casting 106, just beneath the cover plate 502. Pivotally mounted on studs 644 which project upwardly from the carriage 624 are two bell-crank levers 646 and each of the heel seat wipers 50 is connected to an arm of one of these levers by means of a link 648, Fig. 3. Mounted on the other arm of each of these bell-crank levers is a cam roll 650 which is received within a cam groove 652 formed in a cam plate 654. The cam plate 654 has on its upper surface a rib 656 which is re-

ceived within a groove 658 formed in the lower side of the cover plate 502, Fig. 29. A pair of clamp screws 660, which pass through elongated openings 661 in the plate 502, are threaded into the cam plate 654. When these screws are loosened, the cam plate may be adjusted relatively to the cover plate by means of an eccentric stud 662 which is mounted on the cover plate by means of a binding nut 664. As will be apparent, when the carrier 624 is advanced, by fluid pressure operated means which are about to be described, from the retracted position in which it is shown in Fig. 3, the cam grooves 652 are so shaped and disposed that the heel seat wipers 50, 50 will be swung from the open positions in which they are shown in Fig. 3 to the closed positions in which they are shown in Fig. 28.

In order to reduce the load imposed upon the cam grooves 652, 652, the following arrangement is provided. Secured to the outer edge of the carrier 624, by screws 670, 670, are two cylinders 672, 672, Figs. 3 and 29, and fitted in each of these cylinders is a piston 674 having a forwardly extending rod 676. Fastened to each of these piston rods is a plate 678 which is slidable in a groove 680 formed in the carrier 624. Mounted on the arm of each bell-crank lever to which the link 648 is connected, is a roller 682 which rides in one of the aforementioned grooves 680. Connected to each of the cylinders is a conduit 684. As will presently appear, fluid under pressure is admitted to these two conduits at the same time in the operating cycle of the machine as it is admitted to the fluid pressure operated means for advancing the carrier 124. Thus the force required to swing the heel seat wipers to closed position is provided by the pistons 674, and the cam grooves 652, in effect, merely serve to control this closing action.

On its lower side the carrier 624 is provided with two downwardly projecting lugs 690, Figs. 8 and 18, and these lugs are connected, by means of links 692, to the upwardly extending arm of a bell-crank lever 694. This bell-crank lever is pivotally mounted on a cross shaft 696, carried by downwardly extending ears 698 on the lower head casting 106. This bell-crank lever has a horizontally extending arm which is connected, by means of a pair of links 700 to an outwardly extending pair of ears 702 formed integrally with a sleeve member 704, Fig. 5. This sleeve member is slidable on the outer surface of the cylinder 146 and is closed at its lower end by means of a tubular head 706. Extending downwardly from the cylinder 146 is a stem 708 which passes through the head 706 and has threaded onto its lower end an adjusting nut 710. This nut is slidable in a guide bearing 712, secured to a portion of the frame 102 and surrounding the stem 708, and slidable within the tubular head is a sealing gland 714. Connected to a bore 716 in the stem 708, which terminates at its upper end in a radial passage 718 in communication with the space above the head 706, is a conduit 720, while connected to the space in the tubular head above the gland 714 is a conduit 722. When fluid under pressure is admitted through the conduit 720 to the space above the tubular head 706 and simultaneously exhausted through the conduit 722 from the space above the gland 714, the sleeve 704 will be moved downwardly. As a result of such downward movement of this sleeve, the bell-crank lever 694 will be rocked in a counterclockwise direction, Fig. 18, and the wiper carrier 624 will be advanced from the retracted position in which it is shown in Fig. 3 to the position in which it is shown in Fig. 28. Conversely, when fluid under pressure is exhausted through the conduit 720 and admitted through the conduit 722, the wiper carrier will be retracted to the position shown in Fig. 3. The conduit 720 is connected to a conduit 726, Fig. 33, to which the conduits 684, 684, previously referred to, are also connected. Thus, the pistons 674, 674 will be operated simultaneously with the advance of the wiper carrier 624 for the purpose explained above.

There are eight shank wipers 60 on each side of the machine and each group of eight shank wipers is associated with a carrier 730, Fig. 3. These carriers are slidably mounted in guideways 732, 732 formed in the lower head casting 106 and are held in place by means of gibbs 734, 736, Figs. 16 and 21. Extending downwardly from each of these carriers is an arm 738, Fig. 21, which projects through a clearance hole 740, Fig. 3, in the head casting 106. Each of these arms is connected, by means of a pair of links 742, 742 to the vertically extending arm of a bell-crank lever 744. The bell-crank levers 744 are each pivotally mounted on the frame construction 102 and have horizontally extending arms which are connected to the sleeve 704 by means of links 746, Fig. 2. Thus, when the sleeve 704 is moved downwardly in the manner explained above to advance the heel wiper carrier 624, the shank wiper carriers 730, 730 will be moved inwardly toward each other to advance the shank wipers 60. Formed integrally on the upper side of each wiper carriers 730 is a cross slide 750 on which there is slidably mounted a shank wiper supporting member 752, Figs. 16, 18, 19, 20 and 21. Rising vertically from this supporting member is a web 754 having an arcuate front edge 756, Fig. 21.

Each of the shank wipers is formed as a flexible blade having a thickened operating end 760 and a cylindrical shaft portion 764, Fig. 24. These shaft portions form the crossbars of a chain 763 which is provided with side links 766, Figs. 19 and 21. At one end this chain is connected to an anchor block 768 by means of a pin 770, Fig. 21, this block being secured to the wiper carrier 730 by means of screws 772, Fig. 19. Pivotally mounted on one side of the web 754 on a fulcrum pin 774, Figs. 19 and 20, which is in alignment with the pin 770, is a shank wiper control member 776. This control member 35 has extending therefrom two parallel webs 778, 780 forming an arcuate guideway 782 in which the chain 763 is received. A keeper plate 784 attached to the web 778 fits between the side links of the chain and holds the wiper assembly in place. Outward thrust on the shank 40 wipers 60 is resisted by flanges 788 formed on the wipers and bearing against the outer edges of the webs 778, 780, Fig. 19, see also Fig. 24. As will be apparent, the steepness of the curve formed by the outer operating ends 760 of the shank wipers 60 may be varied by swinging the control member 776 about the axis of the fulcrum pin 774. For this purpose each of the control members 776 has a finger grip 796 and is provided with a spring-pressed pawl 792 which is adapted to engage 45 ratchet teeth 794 cut in the arcuate surface of the web 754. As will presently appear, each of the control members 776 is urged yieldingly in a clockwise direction, Fig. 21, so that the pawl and the ratchet teeth will hold it in different positions of adjustment. Also associated 50 with each control member is a finger 796 which moves over a calibrated scale 798 on the web 754.

The shank wiper supporting members 752 are each provided with a groove 800 which receives a roll 802 mounted on one of the two slides 496, Figs. 16, 19 and 28. Thus, when these slides are advanced, at an intermediate point in the operating cycle of the machine and after the shank retarding fingers 74, 76 have been moved to their operating positions as shown in Fig. 25, the supporting members will also be moved forwardly against the resistance of return springs 804, Figs. 16 and 19. 60 The extent of such forward movement of the shank wiper supporting members is limited by the engagement of the shank retarder fingers 76, 76 on each side of the machine with the upwardly curving shank portion on opposite sides of the shoe. As has already been explained, the blocks 550, 550 with which the shank retarder fingers 76, 76 are associated, are urged yieldingly upward, relatively to the blocks 494, 494 which are formed integrally on the forward ends of the slides 496, 496, by means of springs 556. For limiting the extent of 65 such upward movement of the blocks 550 and hence of 70 75

the associated shank retarder fingers 76, each of these blocks is provided with a forwardly extending abutment 810, Figs. 16 and 18, while each of the shank wiper control members 776 carries a curved ledge member 812 which extends laterally over the abutment 810 on the adjacent block 556. Hence, when the shank wiper control members are adjusted to vary the steepness of the curvature of the operating ends of the shank wipers 60, 60, the vertical positions of the shank retarder fingers 76, 76 will be correspondingly altered.

For advancing the slides 496, 496, each of these slides is provided with a central bore 820, Figs. 22 and 23, in which there is received a piston 822. This piston is formed on one end of a hollow rod 824, the other end of which is supported in a block 826, secured to the cover plate 502 by screws 828. Fitted within the hollow rod 824 is a tube 830 which opens at one end through the piston 822 and is in communication at its other end with a fitting 832 and conduit 834. This tube is spaced from the inside of the hollow rod to provide an annular space 836. This annular space is in communication at one end, through ports 840, with the bore 820 between the piston 822 and a sealing member 842, which closes one end of the bore 820, and at its other end, through ports 844, with a passage 846 in the block 826 to which a conduit 848 is connected. When fluid under pressure is admitted through conduits 834, Fig. 16, and exhausted through conduits 848, the slides 496, 496 will be advanced. Should either one of these two slides tend to stick in its guideways, it will be picked up and moved along by the other slide through the action of the roll 506 and slot 508.

At their forward ends, the telescoping intermediate wipers 638, 638 are each pivotally connected to a shank wiper 860 by means of a pivot pin 862, Fig. 29. The wipers 860, 860 are each secured to their respective wiper carriers by means of screws 864, Figs. 3, 16, 24 and 28. On their lower sides, these telescoping wipers are substantially flush with the lower operating faces of the heel seat wipers 50, 50 and, during the advancing movements of the heel seat wiper carrier 624 and of the shank wiper carriers 730, 730, the wipers 638, 638 telescope into the wipers 50, 50 so that a substantially uninterrupted wiping surface is presented to the upper materials around the heel seat and along the opposite shank portions of the shoe. Each of the heel seat wipers is provided with a semi-cylindrical recess 866, Fig. 29, which fits over a semi-cylindrical projection 868 on its associated wiper 860 when the heel seat wipers have been fully advanced and closed, see Fig. 28. Secured to the lower side of the cover plate 502 is a wear plate 870 which bears against the upper sides of the heel seat wipers 50, 50, Fig. 18, and also against the upper sides of the shank wipers 860. On their lower sides each of the heel seat wipers has a recess 874, shaped as shown in Fig. 4, these two recesses, when the heel seat wipers are in the open positions shown in Fig. 3, i. e., when the wiper carrier 622 is retracted, providing a clearance space for an auxiliary or pilot wiper 876 which is secured to the wiper carrier 624 by means of screws 878, Figs. 28 and 29.

Referring particularly to Fig. 33, the fluid pressure system provided for actuating the several pistons mentioned above, and its mode of operation, will now be described. The pump Y, driven by the electric motor Z, draws operating fluid from the sump 100 and delivers it to the main control valve A through a conduit 900, the pressure of the fluid being controlled by the pressure regulating valve X which is of conventional construction, as diagrammatically illustrated in the drawings, a pressure gage 902 being provided to indicate the pressure of the fluid. The valve A has a casing 904 which is provided with two service ports 906, 908 and two exhaust ports 910, 912. Within the valve casing is a valve plunger 914 which is movable from the position in which it is shown for connecting the service port 906 to the conduit 900 and the service port 908 to the exhaust port

912 to a position to the right for connecting the service port 908 to the conduit 900 and the service port 906 to the exhaust port 910. On its left-hand end, the valve plunger 914 has a rod 916 which is connected to one arm 5 of a bell-crank lever 918, pivotally mounted on the casing 904. The other arm of this bell-crank lever is connected, by means of a chain 920, to a foot treadle 922 which is yieldingly held in the elevated position in which it is shown in Fig. 1 by means of a spring 924. As will 10 be apparent, depression of the treadle 922 will shift the valve plunger 914 to the right, return of the valve plunger at the conclusion of an operating cycle being effected by fluid under pressure acting on a small piston 926 associated with the plunger and fitted in a cylinder 928 which 15 is formed in the casing 904 and connected to a conduit 930. Also connected to the bell crank lever 918 is a rod 927 which extends upwardly through a guide bracket 929, Figs. 1 and 2. At its upper end this rod is bent outwardly to provide a handle 931 by means of which 20 the rod may be elevated to return the valve plunger 914 to its original position before the completion of an operating cycle. Leading from the service port 906 is a conduit 940 which is connected to conduits 152, 168, 350, 722 and 848, mentioned above. Also connected to 25 the conduit 940 is a back pressure or relief valve M of conventional construction and diagrammatically illustrated in Fig. 33, which is set to open when the pressure of the fluid in these conduits reaches a predetermined value, approximately 200 p. s. i. This back pressure is 30 sufficient to return pistons 144, 160, 344, slides 496 and the sleeve 704 to their starting or rest positions, as shown in Fig. 33.

The service port 903 of the main control valve A is in communication with a conduit 942 which is connected to 35 a pressure reducing valve B of conventional construction and to a sequence valve D which is also of conventional construction. The outlet of the pressure reducing valve B opens into a conduit 944 which leads to a sequence valve C and has a branch portion 946. This branch portion is in communication, through a locking valve L which will be described below, with the conduit 166 previously referred to as leading into one end of the cylinder 122, see also Fig. 5. The outlet from the sequence valve C is connected to a conduit 948 which is in 40 communication with the conduit 324, previously described as leading to the cylinder 286, see also Fig. 18, and through a dump valve J, with the conduit 410, previously described as leading to the space 414 above the piston 394, see Fig. 11. The conduit 324 has a branch 45 portion 950 in which there is a check valve 952 opening in the direction of the arrow, Fig. 33, this branch portion being in communication with a portion of the conduit 360, previously referred to as being in communication with the conduits 352, Figs. 8 and 9. Leading from the conduit 942 to the sequence valve D is a conduit 954. The outlet of this sequence valve is connected to a conduit 956 one end of which is connected to the inlet of a pressure reducing valve E, while the other end is connected to the inlet of a sequence valve F.

50 The outlet of the pressure reducing valve E is connected to the conduit 154, previously described as leading into the cylinder 146 beneath the piston 144, Fig. 5, and also to the conduit 604 which leads to the cylinder 600, Fig. 12. The outlet from the sequence valve F is 55 in communication with the aforementioned conduit 360, one end of which leads to a sequence valve G, while the other end leads back to the service port 908 of the main control valve A through a check valve 957 which opens in the direction of the arrow in Fig. 33. The outlet of the sequence valve G is connected to a conduit 958 one end of which leads to a pressure reducing valve H while its other end is in communication with the inlet of a sequence valve I. The outlet of the pressure reducing valve H is in communication with the conduit 834, 60 previously described as leading to the bores 820 in the

slides 496, Fig. 22, and a gage 959 is provided for indicating the pressure of the operating fluid in this conduit. The outlet of the sequence valve I opens into the conduit 726 previously described as connected to the cylinders 672, see Fig. 29. This conduit has a branch portion, to which the conduit 720, Fig. 5, is connected, and this branch is in communication with a portion of the conduit 360 through a relief valve K and a check valve 960 which opens in the direction of the arrow, Fig. 33. Also leading from this branch of the conduit 926 is a conduit 962, leading back to the conduit 360 through a check valve 964 which opens in the direction of the arrow, and a conduit 966 associated with the locking valve L. The conduit 930, previously mentioned, is connected to the branch portion of the conduit 726 between the check valve 960 and the relief valve K.

The locking valve L includes a casing 970, Fig. 30, in which there is a plunger 972 provided with an annular groove 973 and a stem 974 which is received in a cylinder 968. A coil spring 976 is arranged to hold the valve plunger 972 yieldingly in the position shown, Figs. 30 and 33, in which the conduit 946 is in communication with the conduit 166. The dump valve J comprises a housing 980, Fig. 32, in which there is mounted a valve plunger 982 normally held in the elevated position in which it is shown by means of a coil spring 984. When the valve plunger is in this elevated position communication between the conduit 324 and the conduit 410 is provided. Slidable in a bore in the upper end of valve plunger 982 is a push rod 986 which is yieldingly connected, by means including a coil spring 988, with the sleeve 704, Fig. 32. Accordingly, when the sleeve 704 is moved downwardly, the valve plunger 982 will be depressed to a position in which communication between the conduits 324 and 410 is shut off while the conduit 410 is connected to an exhaust line 990 which leads back to the sump 100.

As shown in Fig. 31, the five sequence valves C, D, F, G and I are conveniently mounted on a crossbar 992 which extends between two upright portions of the machine frame 102. Preferably, the pressure regulator valve X is set, to limit the pressure of the operating fluid in the conduit 900 to a value of approximately 700 p. s. i., while the several sequence valves are set to open at progressively increasing pressures, e. g., valve C at 215 p. s. i., valve D at 280 p. s. i., valve F at 400 p. s. i., valve G at 450 p. s. i., and valve I at 500 p. s. i. The pressure reducing valve B limits the pressure of the fluid in the conduit 946 to 240 p. s. i., the pressure reducing valve E limits the pressure of the operating fluid in the conduits 154, 604 to 300 p. s. i., while the pressure reducing valve H limits the pressure of the operating fluid in the conduit 834 to 255 p. s. i. As already indicated, the pressure relief valve M is set to open at 200 p. s. i., while the pressure relief valve K is preferably set to open at approximately 650 p. s. i.

As shown in Fig. 33, the various operating pistons are in their rest positions, some of these being returned to these positions by the back pressure set up in the conduit 940 by the relief valve M, while others are retracted by return springs, referred to above. The check valves 957, 952 and 964 provide free flow of operating fluid back to the service port 908, around the plunger 914 and out through the exhaust port 912 when the valve plunger 914 is in the position shown in Fig. 33. Each of the sequence valves is also provided with a free flow return valve for permitting return of the operating fluid to the main control valve A through conduits 958, 956, 954, 944 and 942 in a manner which will be apparent. Upon the depression of the treadle 922 the valve plunger 914 will be shifted to the right thereby connecting the conduit 900 to the service port 908 and at the same time connecting the conduit 940 to exhaust through the service port 906 and the exhaust port 910. As the pressure of the operating fluid builds up in the conduit 942 it is

admitted first through the pressure reducing valve B to the conduits 944 and 946 and directly to the conduit 954. Before the sequence valve C opens, the pressure of the operating fluid in the conduit 166 causes the piston 160 to move to the right, Fig. 5, the locking valve L being at this time open, thus carrying the shoe S which has previously been placed on the carriage 80, rearwardly into the open heel band 84, and then moving the heel band rearwardly until a boss on the bracket 234 strikes the block 316, Fig. 10. Next, the sequence valve C opens and admits operating fluid to the conduits 948, 324 and 410, whereupon the piston 240 is moved forwardly to swing the centralizing fingers 88, 88 into engagement with the opposite sides of the heel end of the shoe, and the plunger 380 is moved downwardly to the extent determined by the setting of the adjustable head piece 384, Figs. 11 and 14. As the plunger 380 descends, the heel retarder fingers 70, 72 will be swung outwardly to their operating positions.

As the pressure of the operating fluid continues to build up in the conduit 954, the sequence valve D soon opens thus admitting operating fluid to the conduit 956 and, through the pressure reducing valve E, to the conduits 154 and 604, whereupon the piston 144 moves the carriage 80 upwardly to press the heel end of the shoe firmly against the button 440 and abutment 442 on the lower end of the plunger 380, Figs. 11 and 12, the force acting on the plunger 380 being considerably greater than that tending to move the carriage and the shoe upwardly, and the piston 590 is operated to move the shank retarder fingers 74, 76 to their operating positions, see Fig. 25. The sequence valve F now opens, causing the pressure of operating fluid in the conduit 360 to move the side clamps 86, 86 inwardly into engagement with the heel band 84 at the opposite sides of the shank portion of the shoe, thereby clamping the upper to the last in these locations. Next, the sequence valve G opens and operating fluid in the conduit 958, passing through the pressure reducing valve H into conduit 834 causes the slides 496, 496 to be advanced until the forward shank retarder fingers 76, 76 strike the bottom of the shoe in the upwardly curving shank portions at the opposite sides of the shoe. Finally, the sequence valve I opens, causing the pressure of operating fluid in the conduit 726 to build up. This operating fluid, admitted to the space in the sleeve 704 above the head portion 706, through the conduit 720 which is connected to the conduit 726, forces the sleeve 704 downwardly, thus advancing and closing the heel seat wipers 50, 50 and advancing the shank wipers 60, 60. During the advancing movement of the heel wipers, pressure of the operating fluid admitted to the cylinders 672, 672 through the conduits 684, 684 acts on the pistons 674, 674 to swing the bell-crank levers 646, Fig. 29, thereby effecting the closing of the heel seat wipers under the control of the cam grooves 652, as previously explained.

Pressure of the operating fluid in the conduit 726 is also effective through the conduit 966 to move the plunger 972 of the locking valve, Fig. 30, to a position to trap operating fluid in the conduit 166 thereby locking the carriage 80 against rearward movement during the operation of the heel wipers 50, 50 and shank wipers 60, 60. As the sleeve 704 continues to descend, and after the heel seat wipers and shank wipers have advanced inwardly over the bottom of the shoe, the plunger 982 of the dump valve J is moved downwardly by the push rod 986 to connect the space above the piston 394 to exhaust and thereby to permit the shoe to be elevated by the pressure of the fluid acting on the piston 144 to press the bottom of the shoe firmly against the wipers. As the pressure of the operating fluid continues to build up in the conduit 726 the relief valve K will eventually be opened thereby admitting the operating fluid to the conduit 930 and thence to the cylinder 928 associated with

the main control valve A. As a result of the pressure of the operating fluid acting on the stem portion 926, the valve plunger 914 will be returned to its original position as shown in Fig. 33. The various operating pistons and elements are now retracted to their original or rest positions by the pressure of the operating fluid in the conduit 940, or by return springs, as previously explained.

The mode of operation of the fluid pressure system and the individual actions of the various operating elements having been explained, the operation of the machine as a whole to last shoes will now be outlined. When the several fluid operated elements are in their rest positions, the carriage 120 will be urged forwardly, i. e., to the left in Fig. 5, by the piston 169, piston rod 162 and shoulder 172 on the piston rod. In loading a shoe into the machine, the operator pulls the carriage still farther outwardly, as permitted by the lost motion afforded by the stop nut 170 and shoulder 172, and places the shoe to be lasted on the carriage with the pin 202 inserted in the last hole and with the toe end of the shoe resting on the toe supporting member 190. Next, after swinging the shoe to line up the heel and shank portions with the center line of the machine, he depresses the shoe against the resistance of the spring 132 and slides the carriage 120 rearwardly until the heel end of the shoe is brought into engagement with the rear portion of the heel band 84 and is inserted beneath the abutment 250, Fig. 5. Upon release of the shoe, the carriage 120 will be elevated to the extent permitted by the abutment 250. The treadle 922 is now depressed and the machine operates in a fully automatic cycle to last the heel seat and shank portions of the shoe after which the lasted shoe is removed from the carriage 120 by the operator and replaced by the next shoe to be lasted.

Immediately after the treadle 922 has been depressed, the piston 169 moves the carriage 120 and the shoe thereon rearwardly, thus causing the heel band to be wrapped snugly around the heel end and opposite shank portions of the shoe, the extent of such rearward movement being limited by the engagement of the bracket 234, Fig. 6, with the block 316 and cylindrical end portion 312 of the piston 240, Figs. 10 and 18. Next, the piston 240 is advanced, thus moving the heel band and shoe forwardly and swinging the centralizing members 88, 88 into engagement with the heel band in the vicinity of the opposite sides of the heel seat of the shoe. As will be apparent, the heel end of the shoe will be centralized in a widthwise direction by the action of the members 88, 88 and also the extent of forward movement of the shoe will be determined by the width of the heel seat of the shoe. Therefore, each shoe, regardless of its size, will be so positioned in a lengthwise direction that the center "x" of the circular heel end of the heel seat, see Fig. 34, is in the same position in the machine, i. e., substantially in vertical alignment with the center of curvature of the groove 622, Fig. 29, about which the heel seat wipers 50, 50 swing, when these wipers are fully advanced and closed. During this forward movement of the piston 240, the cam members 328, 328, Fig. 10, will engage the rollers 246, 246, Fig. 6, and swing the arms 244, 244 downwardly thereby retracting the abutment 250 to an inoperative position, see dotted lines, Fig. 5, in which it is out of the way of the heel seat wipers 50, 50 as they are advanced and closed.

As soon as the shoe has been centered and positioned in a lengthwise direction, the plunger 380 is moved downwardly by the piston 394 and to the extent determined by the setting of the head piece 384, Figs. 11 and 12. Since the subsequent engagement of the bottom of the shoe with the button 440 and abutment 442 will determine the heightwise location of the shoe relatively to the heel seat and shank wipers and accordingly will affect the actions of these wipers as they wipe the upper materials inwardly over the bottom of the shoe, the adjustment of the head piece may be varied, by suitable move-

ment of the rack bar 420, Fig. 13, to accommodate upper materials of different thicknesses. During the downward movement of the plunger 380, the heel seat retarder fingers 70, 72 are swung outwardly to their operating positions directly above the marginal edges of the insole at the opposite sides of the heel seat, see dotted lines in Fig. 11. Now, as the piston 144, Fig. 5, is moved upwardly to elevate the shoe and to press it firmly against the button 440 and abutment 442, these fingers, which when in their operating positions, project a short distance below the level of the button and abutment, are urged upwardly against the resistance of the springs 454, 456, Fig. 15, and serve as insole holdowns for yieldingly pressing the insole i against the last l. Concurrently with the elevation of the shoe by the piston 144, the shank retarding fingers 74, 76 are moved into their operating positions, see Fig. 25, by the piston 399 and are locked in these positions by the toggle links 516, 518.

Next, the side clamps 86, 86, Fig. 8, are moved inwardly by their associated pistons 344, Fig. 9, to cause the heel band 84 to clamp the upper materials against the opposite sides of the last. The slides 496, 496 are now advanced until the foremost shank retarder finger 76 on each side of the machine engages the upwardly curving shank portion of the bottom of the shoe, see Fig. 34. Such forward movement of the slides 496, 496 effects a corresponding movement of the shank wiper control members 776 and, as these control members move forwardly, the upwardly curving operating surface presented by the several shank wipers 60, 60 on each side of the machine is changed in contour and a portion thereof, in effect, displaced in the same direction, each group of shank wipers itself, however, being held against movement in a lengthwise direction by means of the pin 770 and the block 768, Fig. 21. Thus, the curved operating surface of each group of shank wipers is brought substantially into a lengthwise position corresponding to the lengthwise position of the curved shank portion of the shoe on its respective side of the shoe and the contour of the wiping surface is, in effect, determined in accordance with the size of the shoe. Accordingly, if the shank control members 776 have been previously adjusted by swinging movement about the axis of the pin 774 in accordance with the steepness of the curvature of the shank portion of the shoe which, of course, will vary with the style and the heel height of the particular last, see solid and dotted lines, Fig. 35, the curved operating surface of each group of shank wipers will correspond both in steepness and in lengthwise position with the curved shank portion on its side of the shoe as is diagrammatically illustrated in Fig. 35. In this connection, it will be noted that these curved shank portions will be located in different lengthwise positions on shoes of different sizes and on the opposite sides of each shoe, see broken lines, Fig. 34, illustrating a larger shoe S'. However inasmuch as the lengthwise position of the curved operating surface of each group of shank wipers is determined by the engagement of the shank retarder finger 76 on that side of the machine with the curved shank portion on that side of the shoe, variations in the size of the shoe, as well as differences between rights and lefts, will be automatically taken care of as the slides 496, 496 are advanced.

Next, the heel seat wipers 50, 50 are advanced and closed as a result of the downward movement of the sleeve 704 and with the assistance of the pistons 674, and the shank wipers 60, 60 are advanced also as a result of the downward movement of the sleeve 704. As the sleeve 704 begins to descend, the valve plunger 972 of the locking valve L is moved to a position to trap operating fluid in the conduit 166 thereby locking the carriage 120 against rearward movement. During the advancing and closing of the heel seat wipers, the gap which otherwise would exist between the leading sides of the heel seat wipers and the shank wipers 860, 860 is continually closed by

the telescoping wiping members 638, 638 which swing inwardly during the closing movements of the heel seat wipers. In this way, any tendency for the upper materials to wrinkle or to develop into a fold between the heel seat wipers and shank wipers is avoided and a smooth joint between the heel seat and shank portions of the shoe is assured. As the heel seat wipers advance and close the upper materials are forced inwardly against the resistance of the heel seat retarder fingers 70, 72 thereby providing a desired tensioning of the upper materials around the last at the heel end of the shoe. Similarly, as the shank wipers advance, the upper materials are gripped between the outer jaw members 480, 482 and the inner shank retarder fingers 74, 76 and are drawn inwardly over the bottom of the shoe, see Figs. 25 and 26, the toggle links 516 and 518 eventually being broken to permit the shank wipers 60 to project inwardly beneath the fingers 74, 76. During the advancing movement of the wipers and after the wipers have nearly completed their inward movements over the bottom of the shoe, the plunger 982 of the dump valve J is moved downwardly to connect the space above the piston 394, Fig. 11, to exhaust, the pressure of the fluid acting on the piston 144 being now rendered effective to press the bottom of the shoe firmly against the wipers as they complete their advancing movements. Finally, the pressure of the operating fluid opens the valve K and effects movement of the valve plunger 914 of the main control valve back to its original position, and the various operating pistons are returned to their rest positions thus completing the operating cycle.

Having thus described my invention, what I claim as new and desire to secure by Letters Patent of the United States is:

1. A machine for lasting shoes having a pair of end wipers and a pair of side wipers, said end wipers being adapted to be advanced by rectilinear movements in directions extending lengthwise of a shoe being lasted toward said side wipers and to be closed by arcuate swinging movements and said side wipers being adapted to be advanced by rectilinear movements in directions extending transversely of the shoe, and a pair of intermediate wipers, each of said intermediate wipers, respectively, being operatively associated with an end wiper and a side wiper in such a manner that said wipers, as the end wipers are advanced and closed and the side wipers are advanced, present a substantially continuous and uninterrupted wiping surface to the upper materials of the shoe.

2. A lasting machine having a pair of end wipers and a pair of side wipers, said end wipers being adapted to be advanced by rectilinear movements in directions extending lengthwise of a shoe being lasted toward said side wipers and to be closed by arcuate swinging movements and said side wipers being adapted to be advanced by rectilinear movements in directions extending transversely of the shoe, and a pair of intermediate wipers, each of said intermediate wipers, respectively, being pivotally connected to one of said side wipers and slidably received in one of said end wipers, whereby said end, intermediate and side wipers, as the end wipers are advanced and closed and the side wipers advanced, present a substantially continuous and uninterrupted wiping surface to the upper materials of the shoe.

3. A machine for lasting shoes having a pair of heel seat wipers and a pair of side wipers, said heel seat wipers being adapted to be advanced by rectilinear movements in directions extending lengthwise of a shoe being lasted toward said side wipers and to be closed by arcuate swinging movements and side wipers being adapted to be advanced by rectilinear movements in directions extending transversely of the shoe, and a pair of intermediate wipers, each of said intermediate wipers, respectively, being operatively associated with a heel seat wiper and a side wiper in such a manner that said wipers, as the heel seat wipers are advanced and closed and the side wipers advanced,

present a substantially continuous and uninterrupted wiping surface to the upper materials of the shoe.

4. A lasting machine having a pair of heel seat wipers and a pair of side wipers, said heel seat wipers being adapted to be advanced by rectilinear movements in directions extending lengthwise of a shoe being lasted toward said side wipers and to be closed by arcuate swinging movements and said side wipers being adapted to be advanced by rectilinear movements in directions extending transversely of the shoe, and a pair of intermediate wipers, each of said intermediate wipers, respectively, being pivotally connected to one of said side wipers and slidably received in one of said heel seat wipers, whereby said heel seat, intermediate and side wipers, as the heel seat wipers are advanced and closed and the side wipers advanced, present a substantially continuous and uninterrupted wiping surface to the upper materials of the shoe.

5. A machine for lasting shoes having a pair of heel seat wipers and two groups of shank wipers, said heel seat wipers being adapted to be advanced by rectilinear movements in directions extending lengthwise of a shoe being lasted toward said shank wipers and to be closed by arcuate swinging movements and said groups of shank wipers being adapted to be advanced by rectilinear movements in directions extending transversely of the shoe, and a pair of intermediate wipers, each of said intermediate wipers, respectively, being operatively associated with a heel seat wiper and one of the groups of shank wipers in such a manner that said wipers, as the heel seat wipers are advanced and closed and the shank wipers advanced, present a substantially continuous and uninterrupted wiping surface to the upper materials of the shoe.

6. A machine for lasting shoes having a pair of heel seat wipers and two groups of shank wipers, said heel seat wipers being adapted to be advanced by rectilinear movements in directions extending lengthwise of a shoe being lasted toward said shank wipers and to be closed by arcuate swinging movements and said groups of shank wipers being adapted to be advanced by rectilinear movements in directions extending transversely of the shoe, and a pair of intermediate wipers, each of said intermediate wipers, respectively, being pivotally connected to one of the groups of shank wipers and slidably received in one of the heel seat wipers, whereby said heel seat, intermediate and shank wipers, as the heel seat wipers are advanced and closed and the shank wipers are advanced, present a substantially continuous and uninterrupted wiping surface to the upper materials of the shoe.

7. In a lasting machine having a pair of end wipers mounted for rectilinear advancing movements and for arcuate swinging closing movements, means for effecting said rectilinear advancing and arcuate swinging closing movements to the wipers comprising a fluid pressure operated means for exerting a force on each of said wipers tending to move said wipers bodily in a rectilinear direction, additional fluid pressure operated means tending to effect arcuate swinging movements of said wipers, and means operable to control the swinging movements of the wipers in accordance with the advancing movements thereof.

8. In a lasting machine having a pair of end wipers mounted for rectilinear advancing movements and for arcuate swinging closing movements, means for effecting said rectilinear advancing and arcuate swinging closing movements to the wipers comprising a power operated means for exerting a force on each of said wipers tending to move said wipers bodily in a rectilinear direction, a fluid pressure operated means tending to effect arcuate swinging movements of said wipers, and means operable to control the swinging movements of the wipers in accordance with the advancing movements thereof.

9. In a lasting machine having a pair of end wipers mounted for rectilinear advancing movements and for arcuate swinging closing movements, means for effecting said rectilinear advancing and arcuate swinging closing

movements to the wipers comprising a fluid pressure operated means for exerting a force on each of said wipers tending to move said wipers bodily in a rectilinear direction, additional fluid pressure operated means tending to effect arcuate swinging movements of said wipers, and cam means operable to control the swinging movements of the wipers in accordance with the advancing movements thereof.

10. In a lasting machine having a pair of end wipers mounted for rectilinear advancing movements and for arcuate swinging closing movements, means for effecting said rectilinear advancing and arcuate swinging closing movements to the wipers comprising a power operated means for exerting a force on each of said wipers tending to move said wipers bodily in a rectilinear direction, a fluid pressure operated means tending to effect arcuate swinging movements of said wipers, and cam means operable to control the swinging movements of the wipers in accordance with the advancing movements thereof.

11. In a machine for lasting shoes, a support for a shoe to be lasted, a shank wiping unit comprising a wiper carrier mounted for advancing movement toward the shank portion of a shoe on the support, a flexible shank wiping element supported on the carrier and providing a substantially continuous and uninterrupted wiping surface having a flat portion and a curved portion, and a control member associated with the carrier and movable relatively thereto for changing the positions of said flat and said curved portions of the wiping surface in directions extending lengthwise of the shoe to vary the contour of said wiping surface.

12. In a machine for lasting shoes, a support for a shoe to be lasted, a shank wiping unit comprising a wiper carrier mounted for advancing movement toward the shank portion of a shoe on the support, a plurality of articulated shank wiping elements supported on said carrier and contiguously arranged to provide a substantially continuous and uninterrupted wiping surface, and a control member associated with the carrier and movable relatively thereto for varying the positions of said wiping elements to change the contour of said wiping surface.

13. In a machine for lasting shoes, a support for a shoe to be lasted, a shank wiping unit comprising a wiper carrier mounted for advancing movement toward the shank portion of a shoe on the support, a plurality of articulated shank wiping elements supported on said carrier and contiguously arranged to provide a substantially continuous and uninterrupted wiping surface having a flat portion and a curved portion, and a control member associated with the carrier and movable relatively thereto for varying the positions of said wiping elements to change the positions of said flat and said curved portions of the wiping surface in directions extending lengthwise of the shoe thereby to vary the contour of said wiping surface.

14. In a machine for lasting shoes, a support for a shoe to be lasted, a shank wiping unit comprising a wiper carrier mounted for advancing movement toward the shank portion of a shoe on the support, a plurality of articulated shank wiping elements supported on said carrier and contiguously arranged to provide a substantially continuous and uninterrupted wiping surface having a flat portion and a curved portion, and a control member associated with the carrier and movable relatively thereto for varying the positions of said wiping elements to change the angular relationship between said flat portion and said curved portion of the wiping surface thereby to vary the contour of said wiping surface.

15. In a machine for lasting shoes, a support for a shoe to be lasted, a pair of shank wiping units located, respectively, on each side of the support and mounted for advancing movement toward the shank portions of the opposite sides of a shoe on the support, each of said shank wiping units comprising a wiper carrier, a flexible shank wiping element supported on the carrier and providing a substantially continuous and uninterrupted sur-

face having a flat portion and a curved portion, and a control member associated with the carrier and movable relatively thereto for changing the positions of said flat and said curved portions of the wiping surface in directions extending lengthwise of the shoe to vary the contour of said wiping surface.

16. In a machine for lasting shoes, a support for a shoe to be lasted, a pair of wiping units located, respectively, on each side of the support and mounted for advancing movement toward the shank portions of the opposite sides of a shoe on the support, each of said shank wiping units comprising a wiper carrier, a plurality of articulated shank wiping elements supported on said carrier and contiguously arranged to provide a substantially continuous and uninterrupted wiping surface, and a control member associated with the carrier and movable relatively thereto for varying the positions of said wiping elements to change the contour of said wiping surface.

17. In a machine for lasting shoes, a support for a shoe to be lasted, a pair of wiping units located, respectively, on each side of the support and mounted for advancing movement toward the shank portions of the opposite sides of a shoe on the support, each of said shank wiping units comprising a wiper carrier, a plurality of articulated shank wiping elements supported on said carrier and contiguously arranged to provide a substantially continuous and uninterrupted wiping surface having a flat portion and a curved portion, and a control member associated with the carrier and movable relatively thereto for varying the positions of said wiping elements to change the positions of said flat and said curved portions of the wiping surface in directions extending lengthwise of the shoe thereby to vary the contour of said wiping surface.

18. In a machine for lasting shoes, a support for a shoe to be lasted, a pair of wiping units located, respectively, on each side of the support and mounted for advancing movement toward the shank portions of the opposite sides of a shoe on the support, each of said shank wiping units comprising a wiper carrier, a plurality of articulated shank wiping elements supported on said carrier and contiguously arranged to provide a substantially continuous and uninterrupted wiping surface having a flat portion and a curved portion, and a control member associated with the carrier and movable relatively thereto for varying the positions of said wiping elements to change the angular relationship between said flat portion and said curved portion of the wiping surface to vary the contour of said wiping surface.

19. In a machine for lasting shoes, a support for a shoe to be lasted, a shank wiping unit comprising a wiper carrier mounted for advancing movement toward the shank portion of a shoe on the support, a flexible shank wiping element supported on the carrier and providing a substantially continuous and uninterrupted wiping surface having a flat portion and a curved portion, a control member associated with the carrier and movable relatively thereto for changing the positions of said flat and said curved portions of the wiping surface in directions extending lengthwise of the shoe to vary the contour of said wiping surface, power-operated means for effecting movement of the control member relatively to the carrier prior to movement of the carrier toward the shank portion of the shoe, and means movable with the control member and engageable with the curved part of the shank portion of the shoe to limit the movement of the control member and thereby to determine the contour of the wiping surface in accordance with the size of the shoe being lasted.

20. In a machine for lasting shoes, a support for a shoe to be lasted, a shank wiping unit comprising a wiper carrier mounted for advancing movement toward the shank portion of a shoe on the support, a plurality of articulated shank wiping elements supported on the carrier and contiguously arranged to provide a substantially continuous and uninterrupted wiping surface, a control

member associated with the carrier and movable relatively thereto for varying the positions of said wiping elements to change the contour of said wiping surface, power-operated means for effecting movement of the control member relatively to the carrier prior to movement of the carrier toward the shank portion of the shoe, and means movable with the control member and engageable with the curved part of the shank portion of the shoe to limit movement of the control member and thereby to determine the contour of the wiping surface in accordance with the size of the shoe being lasted.

21. In a machine for lasting shoes, a support for a shoe to be lasted, a shank wiping unit comprising a wiper carrier mounted for advancing movement toward the shank portion of a shoe on the support, a plurality of articulated shank wiping elements supported on the carrier and contiguously arranged to provide a substantially continuous and uninterrupted wiping surface having a flat portion and a curved portion, a control member associated with the carrier and movable relatively thereto for varying the positions of said wiping elements to change the positions of said flat and said curved portions of the wiping surface in directions extending lengthwise of the shoe thereby to vary the contour of said wiping surface, power-operated means for effecting movement of the control member relatively to the carrier prior to movement of the carrier toward the shank portion of the shoe, and means movable with the control member and engageable with the curved part of the shank portion of the shoe to limit movement of the control member and thereby to determine the contour of the wiping surface in accordance with the size of the shoe being lasted.

22. In a machine for lasting shoes, a support for a shoe to be lasted, a pair of shank wiping units located, respectively, on each side of the support and mounted for advancing movement toward the shank portions of the opposite sides of a shoe on the support, each of said shank wiping units comprising a wiper carrier, a flexible shank wiping element supported on the carrier and providing a substantially continuous and uninterrupted wiping surface having a flat portion and a curved portion, a control member associated with the carrier and movable relatively thereto for changing the positions of said flat and said curved portions of the wiping surface in directions extending lengthwise of the shoe to vary the contour of said wiping surface, power-operated means for effecting movement of the control member relatively to the carrier prior to movement of the carrier toward the shank portion of the shoe, and means movable with the control member and engageable with the curved part of the shank portion of the shoe to limit the movement of the control member and thereby to determine the contour of the wiping surface in accordance with the size of the shoe being lasted.

23. In a machine for lasting shoes, a support for a shoe to be lasted, a pair of shank wiping units located, respectively, on each side of the support and mounted for advancing movement toward the shank portions of the opposite sides of a shoe on the support, each of said shank wiping units comprising a wiper carrier, a plurality of articulated shank wiping elements supported on the carrier and contiguously arranged to provide a substantially continuous and uninterrupted wiping surface, a control member associated with the carrier and movable relatively thereto for varying the positions of said wiping elements to change the contour of said wiping surface, power-operated means for effecting movement of the control member relatively to the carrier prior to movement of the carrier toward the shank portion of the shoe, and means movable with the control member and engageable with the curved part of the shank portion of the shoe to limit movement of the control member and thereby to determine the contour of the wiping surface in accordance with the size of the shoe being lasted.

24. In a machine for lasting shoes, a support for a

shoe to be lasted, a pair of shank wiping units located, respectively, on each side of the support and mounted for advancing movement toward the shank portions of the opposite sides of a shoe on the support, each of said shank wiping units comprising a wiper carrier, a plurality of articulated shank wiping elements supported on the carrier and contiguously arranged to provide a substantially continuous and uninterrupted wiping surface having a flat portion and a curved portion, a control member associated with the carrier and movable relatively thereto for varying the positions of said wiping elements to change the positions of said flat and said curved portions of the wiping surface in directions extending lengthwise of the shoe to vary the contour of said wiping surface, power-operated means for effecting movement of the control member relatively to the carrier prior to movement of the carrier toward the shank portion of the shoe, and means movable with the control member and engageable with the curved part of the shank portion of the shoe to limit movement of the control member and thereby to determine the contour of the wiping surface in accordance with the size of the shoe being lasted.

25. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, and a retarder finger associated with said abutment and movable therewith heightwise of the shoe toward a position for engagement with the insole, said retarder finger being mounted for yielding movement heightwise of the shoe relatively to said abutment in response to pressure exerted thereon by the insole during a relative movement of the abutment and support prior to engagement of the abutment with the insole.

26. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, and a plurality of retarder fingers associated with said abutment and movable therewith heightwise of the shoe toward a position for engagement with the insole, said retarder fingers being mounted for yielding movement heightwise of the shoe relatively to said abutment in response to pressure exerted thereon by the insole during a relative movement of the abutment and support prior to engagement of the abutment with the insole.

27. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, a plunger mounted adjacent to said abutment for sliding movement in a direction extending heightwise of the shoe and relatively to the abutment, cooperating stop means on the abutment and plunger adapted to provide a limited amount of movement of said plunger relatively to said abutment, spring means for resisting such relative movement in one direction, and a retarder finger mounted on said plunger, said retarder finger being arranged to engage the marginal edge of the insole and to be moved yieldingly heightwise of the shoe relatively to said abutment against the re-

sistance of said spring means during a relative movement of the abutment and support prior to engagement of the abutment with the insole.

28. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, a pair of plungers mounted adjacent to said abutment for sliding movement in a direction extending heightwise of the shoe and relatively to the abutment, cooperating stop means on the abutment and said plungers adapted to provide a limited amount of movement of said plungers relatively to said abutment, spring means for resisting such relative movement in one direction, and a retarder finger mounted on each of said plungers, said retarder fingers being arranged to engage the marginal edge of the insole and to be moved yieldingly heightwise of the shoe relatively to said abutment against the resistance of said spring means during a relative movement of the abutment and support prior to engagement of the abutment with the insole.

29. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, a plunger mounted adjacent to said abutment for sliding movement in a direction extending heightwise of the shoe and relatively to said abutment, cooperating stop means on the abutment and plunger adapted to provide a limited amount of movement of said plunger relatively to said abutment, spring means for resisting such relative movement in one direction, a retarder finger pivotally supported on said plunger, and yieldable means connected to the finger and adapted to swing the finger to an operative position in response to heightwise movement of the plunger toward the shoe, said retarder finger being arranged to engage the marginal edge of the insole and to be moved yieldingly heightwise of the shoe and relatively to the abutment, against the resistance of said spring means, during a relative movement of the abutment and support prior to engagement of the abutment with the insole and to be swung inwardly during the operation of said heel seat wiper against the resistance of said yieldable means.

30. In a machine for lasting shoes, a support for a shoe to be lasted, a pair of heel seat wipers, an abutment member for engaging the heel seat portion of the insole of a shoe on the support to determine the heightwise position of the heel seat of the shoe relatively to said wipers, said abutment being mounted for movement in a direction extending heightwise of the shoe from an inoperative position, remote from the shoe, to an operative position for engagement with the shoe, a pair of plungers mounted adjacent to said abutment for sliding movements in directions extending heightwise of the shoe, cooperative stop means on the abutment and said plungers adapted to provide a limited amount of movement of said plungers relatively to said abutment, spring means for resisting such relative movement in one direction, a retarder finger pivotally supported on each of said plungers, and yieldable means connected to the fingers and adapted to swing the fingers to operative positions in response to heightwise movement of the plunger toward the shoe, said retarder fingers being arranged to engage the marginal edge of the insole and to be moved yieldingly heightwise of the shoe relatively to the abutment, against the resistance of

said spring means, during a relative movement of the abutment and support prior to engagement of the abutment with the insole and to be swung inwardly during the operation of said heel seat wiper against the resistance of said yieldable means.

31. In a lasting machine, a wiper mounted for movement to wipe the lasting margin of the upper materials of a shoe inwardly over the bottom of the shoe, a retarder finger adapted to engage the marginal edge of the insole of the shoe and mounted for movement inwardly from the edge of the insole in response to the inward wiping of the upper materials by said wiper, spring means for yieldably resisting such inward movement of the retarder finger, means for releasably connecting said spring means to said finger, and means operable during inward movement of said finger for releasing said spring means.

32. In a lasting machine, a wiper mounted for movement to wipe the lasting margin of the upper materials of a shoe inwardly over the bottom of the shoe, a retarder finger adapted to engage the marginal edge of the insole of the shoe and mounted for movement inwardly from the edge of the insole in response to the inward wiping of the upper materials by said wiper, spring means for yieldably resisting such inward movements of the retarder finger, and means including a pair of toggle links for releasably connecting said spring means to said finger.

33. In a lasting machine, a wiper mounted for movement to wipe the lasting margin of the upper materials of a shoe inwardly over the bottom of the shoe, a retarder finger adapted to engage the marginal edge of the insole of the shoe and mounted for pivotal movement inwardly from the edge of the insole in response to the inward wiping of the upper materials by said wiper, spring means for yieldably resisting such inward pivotal movement of the retarder finger, means for releasably connecting said spring means to said finger, and means operable during inward movement of said finger for releasing said spring means.

34. In a lasting machine, a wiper mounted for movement to wipe the lasting margin of the upper materials of a shoe inwardly over the bottom of the shoe, a retarder finger adapted to engage the marginal edge of the insole of the shoe and mounted for pivotal movement inwardly from the edge of the insole in response to the inward wiping of the upper materials by said wiper, spring means for yieldably resisting such inward pivotal movement of the retarder finger, and means including a pair of toggle links for releasably connecting said spring means to said finger.

35. In a lasting machine, a wiper mounted for movement to wipe the lasting margin of the upper materials of a shoe inwardly over the bottom of the shoe, a retarder finger adapted to engage the marginal edge of the insole of the shoe and mounted for movement inwardly from the edge of the insole in response to the inward wiping of the upper materials by said wiper, spring means for yieldably resisting such inward movement of the retarder finger, a pair of links forming a toggle for connecting said spring means to said finger, and means operable during the inward movement of said finger by the wiper for breaking the toggle to release the finger from the action of said spring means.

36. In a lasting machine, a wiper mounted for movement to wipe the lasting margin of the upper materials of a shoe inwardly over the bottom of the shoe, a retarder finger adapted to engage the marginal edge of the insole of the shoe and mounted for pivotal movement inwardly from the edge of the insole in response to the inward wiping of the upper materials by said wiper, spring means for yieldably resisting such inward pivotal movement of the retarder, a pair of links forming a toggle for connecting said spring means to said finger, and means operable during the inward movement of said finger by the wiper for breaking the toggle to release the finger from the action of said spring means.

37. In a lasting machine, a wiper mounted for movement to wipe the lasting margin of the upper materials of a shoe inwardly over the bottom of the shoe during an automatic cycle of operations of the machine, a retarder finger adapted when in operative position to engage the marginal edge of the insole and mounted for movement inwardly from the edge of the insole in response to the inward wiping of the upper materials by said wiper, spring means for yieldably resisting such inward movement of the retarder finger, a pair of links arranged to be straightened when said finger is moved to operative position for releasably connecting said spring means to the finger, and means operable during the inward movement of said finger for breaking the toggle formed by said links to release the finger from the action of said spring means.

38. In a lasting machine, a wiper mounted for movement to wipe the lasting margin of the upper materials of a shoe inwardly over the bottom of the shoe during an automatic cycle of operations of the machine, a retarder finger adapted when in operative position to engage the marginal edge of the insole and mounted for pivotal movement inwardly from the edge of the insole in response to the inward wiping of the upper materials by said wiper, spring means for yieldably resisting such inward pivotal movement of the retarder finger, a pair of links arranged to be straightened when said finger is moved to operative position for releasably connecting said spring means to the finger, and means operable during the inward movement of said finger for breaking the toggle formed by said links to release the finger from the action of said spring means.

39. In a lasting machine, a wiper mounted for movement to wipe the lasting margin of the upper materials of a shoe inwardly over the bottom of the shoe during an automatic cycle of operations of the machine, a retarder finger adapted when in operative position to engage the marginal edge of the insole and mounted for movement inwardly from the edge of the insole in response to the inward wiping of the upper materials by said wiper, spring means for yieldably resisting such inward movement of the retarder finger, a pair of links arranged to be straightened when said finger is moved to operative position for releasably connecting said spring means to the finger, means for automatically moving the finger to its operative position and for straightening said links prior to the operation of said wiper, and means operable during the inward movement of said finger for breaking the toggle formed by said links to release the finger from the action of said spring means.

40. In a lasting machine, a wiper mounted for movement to wipe the lasting margin of the upper materials of a shoe inwardly over the bottom of the shoe during an automatic cycle of operations of the machine, a retarder finger adapted when in operative position to engage the marginal edge of the insole and mounted for pivotal movement inwardly from the edge of the insole in response to the inward wiping of the upper materials by said wiper, spring means for yieldably resisting said inward pivotal movement of the retarder finger, a pair of links arranged to be straightened when said finger is moved to operative position for releasably connecting said spring means to the finger, means for automatically moving the finger to its operative position and for straightening said links prior to the operation of said wiper, and means operable during the inward movement of said finger for breaking the toggle formed by said links to release the finger from the action of said spring means.

41. In a machine for lasting shoes, a wiper mounted for movement to wipe the lasting margin of the upper materials of a shoe inwardly over the bottom of the shoe in the shank portion thereof during an automatic cycle of operations of the machine, a retarder finger for engaging the marginal edge of the insole of the shoe

in the upwardly curving part of its shank portion, said retarder finger being initially positioned in a location remote from its point of engagement with the insole in directions extending heightwise and lengthwise of the shoe, and means operable during an initial stage in the cycle of operations of the machine for bringing said finger into engagement with the insole by movements in directions extending first heightwise and then lengthwise of the shoe.

42. In a machine for lasting shoes, wipers mounted for movement to wipe the lasting margin of the upper materials of a shoe inwardly over the bottom of the shoe in the shank portions at the opposite sides thereof during an automatic cycle of operations of the machine, a pair of retarder fingers for engaging the marginal edges of the insole of the shoe in the upwardly curving parts of its shank portion, said retarder fingers being initially positioned in locations remote from their points of engagement with the insole in directions extending heightwise and lengthwise of the shoe, and means operable during an initial stage in the cycle of operations of the machine for bringing said fingers into engagement with the insole by movement in directions extending first heightwise and then lengthwise of the shoe.

43. In a machine for lasting shoes, a wiper mounted for movement to wipe the lasting margin of the upper materials of a shoe inwardly over the bottom of the shoe in the shank portion thereof during an automatic cycle of operations of the machine, a retarder finger for engaging the marginal edge of the insole of the shoe in the upwardly curving part of its shank portion, said retarder finger being initially positioned in a location remote from its point of engagement with the insole in directions extending heightwise and lengthwise of the shoe, and fluid pressure actuated means operable during an initial stage in the cycle of operations of the machine for bringing said finger into engagement with the insole by movements in directions extending first heightwise and then lengthwise of the shoe.

44. In a machine for lasting shoes, wipers mounted for movement to wipe the lasting margin of the upper materials of a shoe inwardly over the bottom of the shoe in the shank portions at the opposite sides thereof during an automatic cycle of operations of the machine, a pair of retarder fingers for engaging the marginal edges of the insole of the shoe in the upwardly curving parts of its shank portion, said retarder fingers being initially positioned in locations remote from their points of engagement with the insole in directions extending heightwise and lengthwise of the shoe, and fluid pressure actuated means operable during an initial stage in the cycle of operations of the machine for bringing said fingers into engagement with the insole by movements in directions extending first heightwise and then lengthwise of the shoe.

45. In a machine for lasting shoes, a support for a shoe to be lasted, wipers mounted for movement to wipe the lasting margin of the upper materials of a shoe on the support inwardly over the bottom of the shoe, power operated means for thus moving the wipers, an abutment member movable in a direction heightwise of the shoe and adapted to engage the bottom of the shoe to determine the position of the shoe relatively to said wipers, fluid pressure operated means for thus moving said member, power operated means for moving said support in a direction extending heightwise of the shoe to press the bottom of the shoe against said abutment member and to support the shoe against the pressure exerted thereon by the wipers as the upper materials are wiped inwardly over the bottom of the shoe, and means for controlling the action of said fluid pressure operated means during the inward movement of the wipers to reduce the force exerted on the shoe by said abutment member and thereby

to cause the power operated means for moving the support to press the shoe against the wipers with increased force.

46. In a machine for lasting shoes, a support for a shoe to be lasted, wipers mounted for movement to wipe the lasting margin of the upper materials of a shoe on the support inwardly over the bottom of the shoe, power operated means for thus moving the wipers, an abutment member movable in a direction heightwise of the shoe and adapted to engage the bottom of the shoe to determine the position of the shoe relatively to said wipers, fluid pressure operated means for thus moving said member, power operated means for moving said support in a direction extending heightwise of the shoe to press the bottom of the shoe against said abutment member and to support the shoe against the pressure exerted thereon by the wipers as the upper materials are wiped inwardly over the bottom of the shoe, and valve means for controlling the action of said fluid pressure operated means during the inward movement of the wipers to reduce the force exerted on the shoe by said abutment member and thereby to cause the power operated means for moving the support to press the shoe against the wipers with increased force.

47. In a machine for lasting shoes, a support for a shoe to be lasted, wipers mounted for movement to wipe the lasting margin of the upper materials of a shoe on the support inwardly over the bottom of the shoe, power operated means for thus moving the wipers, an abutment member movable in a direction heightwise of the shoe and adapted to engage the bottom of the shoe to determine the position of the shoe relatively to said wipers, fluid pressure operated means for thus moving said member, power operated means for moving said support in a direction extending heightwise of the shoe to press the bottom of the shoe against said abutment member and to support the shoe against the pressure exerted thereon by the wipers as the upper materials are wiped inwardly over the bottom of the shoe, means including a conduit for supplying fluid under pressure to said fluid pressure operated means, a valve in said conduit having a plunger operable in a first position to connect said fluid pressure operated means to a source of fluid under pressure and in a second position to connect said fluid pressure operated means to exhaust, and means for moving said valve plunger to said second position during the inward movement of the wipers to reduce the force exerted on the shoe by said abutment member and thereby to cause the power operated means for moving the support to press the shoe against the wipers with increased force.

48. In a machine for lasting shoes, wipers for wiping the lasting margin of the upper materials of a shoe inwardly over the bottom of the shoe, a movably mounted support for a shoe on its last, power operated means for effecting movement of said support from a loading position to an operative position, and means controlled in accordance with the size of the shoe on the support for variably determining the extent of movement of the support to cause the support when in said operative position to locate each shoe with the center of its heel seat in the same lengthwise position relatively to said wipers regardless of its size.

49. In a machine for lasting shoes, wipers for wiping the lasting margin of the upper materials of a shoe inwardly over the bottom of the shoe, a movably mounted support for a shoe on its last, fluid pressure operated means for effecting movement of the support from a loading position to an operative position, and means controlled in accordance with the size of the shoe on the support for variably determining the extent of movement of the support to cause the support when in said operative position to locate each shoe with the center of its heel seat in the same lengthwise position relatively to said wipers regardless of its size.

50. In a machine for lasting shoes, heel seat wipers

mounted for rectilinear advancing and arcuate closing movements to wipe the upper materials around the heel seat of a shoe inwardly over the bottom of the shoe, a support for a shoe on its last mounted for movement from a loading position to an operative position, power-operated means for effecting movement of said support from the loading position to the operative position, and means controlled in accordance with the size of the shoe on the support for variably determining the extent of movement of the support to cause the support when in said operative position to locate each shoe with the center of its heel seat in the same lengthwise position relatively to said wipers regardless of its size.

51. In a machine for lasting shoes, heel seat wipers mounted for rectilinear advancing and arcuate closing movements to wipe the upper materials around the heel seat of a shoe inwardly over the bottom of the shoe, a support for a shoe on its last mounted for movement from a loading position to an operative position, fluid pressure operated means for effecting movement of said support from the loading position to the operative position, and means controlled in accordance with the size of the shoe on the support for variably determining the extent of movement of the support to cause the support when in said operative position to locate each shoe with the center of its heel seat in the same lengthwise position relatively to said wipers regardless of its size.

52. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the heel seat of the shoe, a movably mounted support for a shoe on its last, power operated means for effecting movement of said support from a loading position to an operative position, and means controlled in accordance with the size of the shoe on the support for variably determining the extent of movement of the support to cause the support when in said operative position to locate each shoe with the center of its heel seat in the same lengthwise position relatively to said wipers regardless of its size.

53. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the heel seat of the shoe, a movably mounted support for a shoe on its last, fluid pressure operated means for effecting movement of said support from a loading position to an operative position, and means controlled in accordance with the size of the shoe on the support for variably determining the extent of movement of the support to cause the support when in said operative position to locate each shoe in the same lengthwise position relatively to said wipers regardless of its size.

54. In a machine for lasting shoes, wipers for wiping the upper materials of a shoe inwardly over the bottom of the shoe, a movably mounted support for a shoe on its last, power operated means for effecting movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position relatively to said wipers regardless of its size.

55. In a machine for lasting shoes, wipers for wiping the upper materials of a shoe inwardly over the bottom

of the shoe, a movably mounted support for a shoe on its last, fluid pressure operated means for effecting movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position, relatively to said wipers, regardless of its size.

56. In a machine for lasting shoes, heel seat wipers mounted for rectilinear advancing and arcuate closing movements to wipe the upper materials of a shoe around the heel seat inwardly over the bottom of the shoe, a movably mounted support for a shoe on its last, power operated means for effecting movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position, relatively to said wipers, regardless of its size.

57. In a machine for lasting shoes, heel seat wipers mounted for rectilinear advancing and arcuate closing movements to wipe the upper materials of a shoe around the heel seat inwardly over the bottom of the shoe, a movably mounted support for a shoe on its last, fluid pressure operated means for effecting movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position, relatively to said wipers, regardless of its size.

58. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the heel seat of the shoe, a movably mounted support for a shoe on its last, power operated means for effecting movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position, relatively to said wipers, regardless of its size.

59. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the heel seat of the shoe, a movably mounted support for a shoe on its last, fluid pressure operated means for effecting

movement of said support from a loading position in which a shoe on the support is located outwardly of the machine from said wipers first inwardly of the machine to a predetermined position and then outwardly of the machine to an operative position, and means controlled in accordance with the size of a shoe on the support for variably determining the extent of such outward movement of the support to cause the support when in said operative position to locate each shoe in the same lengthwise position, relatively to said wipers, regardless of its size.

60. In a machine for lasting shoes, wipers for wiping the lasting margin of the upper materials of a shoe inwardly over the bottom of the shoe, a movably mounted support for a shoe on its last, power operated means for effecting movement of the support from a loading position to an operative position, relatively to said wipers, an abutment member located adjacent to said support for engaging a portion of a shoe on the support to determine the heightwise position of the support and of the shoe thereon prior to the movement of said support by the power operated means, and means for withdrawing said abutment from engagement with the shoe during the movement of said support to operative position.

61. In a machine for lasting shoes, wipers for wiping the lasting margin of the upper materials of a shoe inwardly over the bottom of the shoe, a movably mounted support for a shoe on its last, fluid pressure operated means for effecting movement of the support from a loading position to an operating position relatively to said wipers, an abutment member located adjacent to said support for engaging a portion of a shoe on the support to determine the heightwise position of the support and of a shoe thereon prior to the movement of said support by the fluid pressure operated means, and means for withdrawing said abutment from engagement with the shoe during the movement of said support to operative position.

62. In a machine for lasting shoes, heel seat wipers mounted for advancing and closing movement to wipe the lasting margin of the upper materials around the heel seat of a shoe inwardly over the bottom of the shoe, a movably mounted support for a shoe on its last, power operated means for effecting movement of the support from a loading position to an operating position relatively to said wipers, a band for embracing the heel end of a shoe on the support mounted for movement with the support, an abutment member associated with the band and adapted to engage the heel end of a shoe on the support to determine the heightwise position of the support and of the shoe thereon, relatively to the band, prior to the movement of said support by the power operated means, and means for withdrawing said abutment from engagement with the shoe during the movement of said support to operative position.

63. In a machine for lasting shoes, heel seat wipers mounted for advancing and closing movements to wipe the lasting margin of the upper materials around the heel seat of a shoe inwardly over the bottom of the shoe, a movably mounted support for a shoe on its last, fluid pressure operated means for effecting movement of the support from a loading position to an operative position relatively to said wipers, a band for embracing the heel end of a shoe on the support mounted for movement with the support, an abutment member associated with the band and adapted to engage the heel end of a shoe on the support to determine the heightwise position of the support and of the shoe thereon, relatively to the band, prior to the movement of said support by the fluid pressure operated means, and means for withdrawing said abutment from engagement with the shoe during movement of said support to operative position.

64. In a machine for lasting shoes, wipers for wiping the lasting margin of the upper materials of a shoe inwardly over the bottom of the shoe, a member for en-

gaging the bottom of a shoe to determine the heightwise position of the shoe relatively to said wipers, a movably mounted support for a shoe on its last, power operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and power operated means operable in predetermined time relation to said first power operated means for thereafter effecting movement of said support in a direction extending heightwise of the shoe to bring the bottom of the shoe into engagement with said member.

65. In a machine for lasting shoes, wipers for wiping the lasting margin of the upper materials of a shoe inwardly over the bottom of the shoe, a member for engaging the bottom of a shoe to determine the heightwise position of the shoe relatively to said wipers, a movably mounted support for a shoe on its last, fluid pressure operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and power operated means operable in predetermined time relation to said first power operated means for thereafter effecting movement of said support in a direction extending heightwise of the shoe to bring the bottom of the shoe into engagement with said member.

66. In a machine for lasting shoes, heel seat wipers mounted for rectilinear advancing and arcuate closing movements to wipe the upper materials around the heel seat of a shoe inwardly over the bottom of the shoe, a member for engaging the bottom of the heel seat of the shoe to determine the heightwise position of the shoe relatively to said wipers, a movably mounted support for a shoe on its last, power operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and power operated means operable in predetermined time relation to said first power operated means for thereafter effecting movement of said support in a direction extending heightwise of the shoe to bring the bottom of the shoe into engagement with said member.

67. In a machine for lasting shoes, heel seat wipers mounted for rectilinear advancing and arcuate closing movements to wipe the upper materials around the heel seat of a shoe inwardly over the bottom of the shoe, a member for engaging the bottom of the heel seat of the shoe to determine the heightwise position of the shoe relatively to said wipers, a movably mounted support for a shoe on its last, fluid pressure operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and fluid pressure operated means operable in predetermined time relation to said first fluid operated means

for thereafter effecting movement of said support in a direction extending heightwise of the shoe to bring the bottom of the shoe into engagement with said member.

68. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the shoe, a member for engaging the bottom of the shoe to determine the heightwise position of the shoe relatively to said wipers, a movably mounted support for a shoe on its last, power operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and power operated means operable in predetermined time relation to said first power operated means for thereafter effecting movement of said support in a direction extending heightwise of the shoe to bring the bottom of the shoe into engagement with said member.

69. In a machine for lasting shoes, shank wipers mounted for advancing movements to wipe the upper materials of a shoe inwardly over the bottom of the shoe in the shank portions thereof, heel seat wipers mounted for rectilinear advancing and arcuate closing movements to wipe the upper materials around the heel seat of the shoe inwardly over the bottom of the shoe, a member for engaging the bottom of the shoe to determine the heightwise position of the shoe relatively to said wipers, a movably mounted support for a shoe on its last, fluid pressure operated means for effecting movement of said support in a direction extending lengthwise of the shoe from a loading position to an operative position, means controlled in accordance with the size of the shoe on the support for variably determining the extent of movement of the support to cause the support when in said operative position to locate each shoe with the center of its heel seat in the same lengthwise position relatively to said wipers regardless of its size, and fluid pressure operated means operable in predetermined time relation to said first fluid pressure operated means for thereafter effecting movement of said support in a direction extending heightwise of the shoe to bring the bottom of the shoe into engagement with said member.

70. In a machine for lasting shoes, wipers for wiping the lasting margin of the upper materials of a shoe inwardly over the bottom of the shoe, power operated means for actuating said wipers, a movably mounted support for a shoe on its last, fluid pressure operated means including a cylinder and a piston for effecting movement of said support from a loading position to an operative position, and valve means for trapping operating fluid in said cylinder to lock the support against movement away from its operative position during the actuation of the wipers by said power operated means.

71. In a machine for lasting shoes, wipers for wiping the lasting margin of the upper materials of a shoe inwardly over the bottom of the shoe, fluid pressure operated means for actuating said wipers, a movably mounted support for a shoe on its last, fluid pressure operated means including a cylinder and a piston for effecting movement of said support from loading position to an operative position, and valve means for trapping operating fluid in said cylinder to lock the support against movement away from its operative position during the actuation of the wipers by said first-mentioned fluid pressure operated means.

72. In a machine for lasting shoes, wipers for wiping

conducting operating fluid from a source of fluid under pressure to said cylinder, a normally open valve in said conduit, and means for moving said valve to closed position in response to the actuation of said wipers by the first-mentioned fluid pressure operated means thereby to lock said support against movement away from its operative position during the operation of said wipers.

82. In a machine for lasting shoes, wipers for wiping the lasting margin of the upper materials of a shoe inwardly over the bottom of the shoe, a movable support for a shoe on its last, power operated means for moving the support from an inoperative loading position to an operative position relatively to the wipers, a U-shaped band for embracing an end portion of a shoe on the support when said support is in its loading position, said band being mounted for movement with the support in response to pressure of the shoe thereagainst as the support is moved to operative position, and means associated with the band for yieldingly resisting such movement of the band and for wrapping the band snugly around the end portion of the shoe in response to such movement of the support to operative position.

83. In a machine for lasting shoes, wipers for wiping the lasting margin of the upper materials of a shoe inwardly over the bottom of the shoe, a movable support for a shoe on its last, power operated means for moving the support from an inoperative loading position to an operative position relatively to the wipers, a U-shaped band for embracing an end portion of a shoe on the support when said support is in its loading position, said band being mounted for movement with the support in response to pressure of the shoe thereagainst as the support is moved to operative position, and means associated with the band for yieldingly resisting such movement of the band and for wrapping the band snugly around the end portion of the shoe in response to such movement of the support to operative position.

84. In a machine for lasting shoes, heel seat wipers for wiping the lasting margin of the upper materials around the heel seat of a shoe inwardly over the bottom of the shoe, a movable support for a shoe on its last, power operated means for moving the support from an inoperative loading position to an operative position relatively to the wipers, a U-shaped band for embracing the heel end of a shoe on the support when said support is in its loading position, said band being mounted for movement with the support in response to the pressure of the shoe thereagainst as the support is moved to operative position, and means associated with the band for yieldingly resisting such movement of the band and for wrapping the band snugly around the heel end of the shoe in response to such movement of the support to operative position.

85. In a machine for lasting shoes, heel seat wipers for wiping the lasting margin of the upper materials around the heel seat of a shoe inwardly over the bottom of the shoe, a movable support for a shoe on its last, power operated means for moving the support from an inoperative loading position to an operative position relatively to the wipers, a U-shaped band for embracing the heel end of a shoe on the support when said support is in its loading position, said band being mounted for

movement with the support in response to the pressure of the shoe thereagainst as the support is moved to operative position, and spring means associated with the band for yieldingly resisting such movement of the band and for wrapping the band snugly around the heel end of the shoe in response to such movement of the support to operative position.

86. In a machine for lasting shoes, heel seat wipers for wiping the lasting margin of the upper materials around the heel seat of a shoe inwardly over the bottom of the shoe, shank wipers for wiping the lasting margin of the upper materials along the shank portions at the opposite sides of the shoe inwardly over the bottom of the shoe, a movable support for a shoe on its last, means for moving the support from an inoperative loading position to an operative position relatively to the wipers, a U-shaped band for embracing the heel end and adjacent shank portions of a shoe on the support when said support is in its loading position, said band being mounted for movement with the support in response to pressure of the shoe thereagainst as the support is moved to operative position, and means associated with the band for yieldingly resisting such movement of the band and for wrapping the band snugly around the heel end and adjacent shank portions of the shoe in response to such movement of the support to operative position.

87. In a machine for lasting shoes, heel seat wipers for wiping the lasting margin of the upper materials around the heel seat of a shoe inwardly over the bottom of the shoe, shank wipers for wiping the lasting margin of the upper materials along the shank portions at the opposite sides of the shoe inwardly over the bottom of the shoe, a movable support for a shoe on its last, means for moving the support from an inoperative loading position to an operative position relatively to the wipers, a U-shape band for embracing the heel end and adjacent shank portions of a shoe on the support when said support is in its loading position, said band being mounted for movement with the support in response to pressure of the shoe thereagainst as the support is moved to operative position, and spring means associated with the band for yieldingly resisting such movement of the band and for wrapping the band snugly around the heel end and adjacent shank portions of the shoe in response to such movement of the support to operative position.
